UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC COMPANY, A CORPORATION OF ILLINOIS.

COMMON-BATTERY AUTOMATIC TELEPHONE SYSTEM.

1,332,226.

Specification of Letters Patent.

Patented Mar. 2, 1920.

Application filed January 4, 1906, Serial No. 294,663. Renewed July 2, 1919. Serial No. 308,271.

To all whom it may concern:

Be it known that I, TALBOT G. MARTIN, a citizen of the United States of America, and resident of Chicago, Cook county, Illinois, 5 have invented a certain new and useful Improvement in Common-Battery Automatic Telephone Systems, of which the following is a specification.

My invention relates to telephone systems 10 in general, but more particularly to automatic or semi-automatic telephone systems, and especially to telephone systems of that particular character in which the subscribers of one common battery exchange may call 15 up and obtain connection with the subscribers of another common battery exchange, and wherein the expedient for electrically calling the number of the called subscriber consists in the transmission of electrical im- 20 pulses from the calling subscriber's station to the exchange or central station where the automatic trunk-selecting and line-connecting machinery is located and arranged under the direct control of the different subscribers.

Generally stated, the object of my invention 25 is the provision of an improved and highly efficient telephone system of the foregoing general character.

Special objects of my invention are the 30 provision of an improved common battery apparatus for automatic or semi-automatic telephone systems; the provision of an improved repeater for use in making a trunk-line connection between two common bat- 35 tery automatic telephone exchanges; the provision of an improved connector or line-connecting machine for use in a common battery automatic telephone exchange, and adapted more particularly for use in con- 40 necting up the subscribers of one exchange with those of another exchange; the provision of various improved line and auxiliary circuits for use in connecting one subscriber with another—preferably subscribers 45 of common battery automatic telephone exchanges—as will hereinafter more fully appear; and the provision of certain details and features of improvement tending to increase the general efficiency and serviceabil- 50 ity of a telephone system of this particular character.

To the foregoing and other useful ends, my invention consists in matters hereinafter fully described and claimed.

55 In Figure 1 a sub-station #7000 is repre-

sented connected with a first-selector F¹ and with a repeater R, which two instruments, it will be understood, are part of the apparatus of a central station designated as central station #1.

60 Fig. 2 shows a second-selector S connected with a connector C of my improved design, and the connector connected in turn with the sub-station #2420, which latter is designed to represent the called sub-station, and which is directly connected with the first-selector F², said sub-station #2420, it will be seen, being a member of the exchange system that 65 comprises the central station apparatus shown in Fig. 2, and which will be known 70 as central station #2.

Figs. 1 and 2 taken together represent the 75 sub-station #7000 connected with the sub-station #2420 of the distant exchange, and which former, in the establishment and 80 maintenance of the connection, employs the first-selector F¹ and the repeater R at its own central station #1, and the second-selector S, a connector C and the called first-selector F² at the central station #2.

85 Fig. 3 is a diagrammatic perspective view of the first-selector F¹.

Fig. 4 likewise represents the connector C.

Fig. 5 is a simplified diagram showing the 90 distribution or supply of talking current to 85 the subscribers' lines.

Each central has a battery of its own for the operation of its apparatus. Central station #1 has a battery B¹ and central station #2 has a battery B². The sub-stations employed in connection with common battery systems of the nature in question are all of a well-known and suitable type. Sub-station #7000, for instance, is at once recognized by the peculiar switch-hook 2 which 95 is made with a number of cam-like arms 3, 4, 5 and 6. The primary circuit at said station, when in use, is bridged across the main line, and comprises in series the primary winding 7 of the induction-coil 8, a 100 transmitter 9, a couple of springs 10 and 11 identified with the signaling button 12, and two springs 13 and 14 by means of which the said circuit is maintained closed or opened, depending upon whether the hook is up or 105 down. Said hook is pivoted at one end by the screw 15, and is forced to rise, whenever the weight of the receiver 16 is removed from it, by a suitable switch-hook-spring not shown. The secondary circuit, auxil- 110

iary to the primary, comprises the said receiver in series with the secondary winding 17 of the induction-coil 8, in a permanently closed inductive local circuit. The ringer-circuit at said sub-station includes the ringer 18, the ringer-circuit-springs 19 and 20 and the condenser 21. The circuit, while the switch-hook is down, is closed by the cam-arm 4 that presses the said ringing-circuit-springs into contact, and is normally bridged across the main line. While the hook is up, however, the said bridge is open because the said springs 19 and 20 spring apart after the cam-arm 4 is removed from the spring 19.

The cam-arm 5 controls the continuity of a ground-circuit between the so-called ground-post 22 and ground-terminal G³, by means of two springs 23 and 24 that are included in said circuit. The sub-station has three other springs 25, 26 and 27 which are known as the release-springs and by means of which the main line-conductors may be grounded simultaneously for the purpose of restoring the exchange apparatus in a manner that will be explained. When the hook is depressed, and as it descends, the said release-springs are forced together by the cam-arm 3, which latter then engages the laterally-projecting extremity 28 of the spring 25. The engaging portions of the cam 3 and spring 25 are constructed with their surfaces at an angle with each other, so that as the hook goes down one surface of the projection 28 is engaged by the cam-arm, and when it rises the opposite surface is met. In this way, when the hook goes down, the spring 25 is forced into electric connection with the springs 26 and 27, and when the hook rises it is shoved in the opposite direction.

It should be clear that at the limit of each stroke of the hook the cam-arm 3 clears the spring 25. The calling device employed by the subscriber may be of any suitable or desired character. The type illustrated, however, comprises two push-buttons 29 and 30, two contact-points 31 and 32, two springs 33 and 34 and the ground-post 22. The spring 33 and contact 31 are normally in contact, as well as the spring 34 and contact 32. But when the button 29 is pressed, the spring 33 is separated from the contact-point 31 and connected with the ground-post 22, and when the button 30 is pressed the second spring 34 is pressed onto the same ground-post, after said spring leaves the contact-point 32. The signaling button 12 has a grounded contact-point 35 associated with it onto which the spring 11 is forced whenever the said button is pressed.

In Fig. 3 the first-selector F¹ is shown with the bank 50 of trunk-line-terminals beneath it, while the private-bank 51 is located just above the trunk-line-bank. The switch-shaft 52 is vertically disposed on the front of the switch-frame and retained con-

nected therewith by bearings which are not shown. The shaft may be moved endwise in said bearings and then rotated by ratchet and pawl electro-magnetically-operated mechanism, the endwise step-by-step movements occurring first. Among the functions of the shaft, an important one is the holding of the line-wipers 53 and 54, and of the private-wiper 55. The former two comprise a set distinct from the latter, but both sets are located within range of the contacts of their respective banks 50 and 51. Said wipers are not only insulated from the shaft, but from each other as well. Among the details that are associated with the shaft is a cam-piece 56 which is of a split sleeve design and secured to the shaft by a screw 57. The general shape of said cam, in section at right angles to the shaft, is that of an oval with the sharper apex on the side farthest away from the said screw. Said cam abuts on a hub 58 that is shrunk to the shaft near the middle of the latter. This hub carries a set of longitudinal teeth 59 that serve, as will be disclosed, to enable the forward rotation of the shaft, and as a locking means against backward rotation of same. On the neck portion of said hub there is found a set of circular teeth 60 that serve in turn as a means by which the raising of the shaft is accomplished, and for locking it when raised. These circular teeth are traversed by a groove 61 into which the end of a so-called shaft-rest 62 normally projects; but when the shaft is rotated any one of the said circular teeth which may be at the proper height slides onto the end of the rest. The end of said rest, of course, is adapted to fit the circular grooves between said circular teeth. The upper surface of the engaging end is level, but the under side is chamfered to form a wedge that corresponds to the upper slope of the circular teeth. Above the hub 58 the shaft carries an arm 63, known as the normal-post-arm, which, while the switch-shaft is at rest, and while the shaft-rest occupies the slot 61, is retained against the normal-post 64 by the coiled spring 65. The said normal-post-arm normally retains an off-normal-spring 66 in contact with a contact-point 67, located beneath it, but when the shaft is raised said spring flexes into contact with a grounded contact-point 68 instead. Among the magnets allotted to the first-selector some are used as relays and others as operating magnets. The magnets 69 and 70 are among the former kind and are known as the vertical and rotary line-relays. By means of their respective armatures 71 and 72 the springs 73 and 74 are controlled with respect to the ground-spring 75. Said springs are comprised in energizing circuits of operating magnets that raise and rotate the shaft. The magnet 76, armature 77, and springs 78, 79

and 80 constitute the bridge-opening-relay, or bridge-cut-off-relay as it is called, and the magnet 81 with its armature 82 and springs 83 and 84 constitutes the back-release-relay, 5 which is used for restoring the switch after it has seized a trunk-line. Of the operating magnets the magnet 85 is known as the vertical-magnet and has allotted to it a so-called vertical-armature 86 that is supported 10 by pivots 87. Whenever the coils 88 and 89 of said vertical-magnet become energized the armature 86 is attracted, and when the magnetization ceases the retracting spring 90 restores said armature to its normal position. 15 The upward movement of the armature is limited by the pole-pieces of the magnet coils 88 and 89, and the lower limit is marked by a section of the switch-frame that passes under the arm 91. Said arm is known 20 as the vertical-arm and extends forwardly from the vertical-armature 86, of which latter it is a part. The vertical-arm carries on its end a so-called vertical-pawl 92 which, when the vertical-armature is attracted, engages 25 with some one of the circular teeth 60 to raise the shaft. Normally, the under surface of the upper section of said pawl rests against a piece that is secured to the switch-frame, and that retains the pawl 30 away from the circular teeth. When the vertical-armature is attracted, as the said pawl rises, a retracting-spring 93 thrusts the upward side of the pawl toward the circular teeth 60. As soon as said pawl clears its 35 normal-rest, and by the time that the vertical-armature strikes the pole-pieces, the vertical-pawl strikes, with the rear surface of its upper section, a bumper piece, which latter constitutes a part of the switch-frame. 40 Therefore, the shaft is thus prevented from being thrown up more than one notch at a time, by its own momentum. It is clear, then, that the pawl 92 not only raises the shaft, but it also acts as a lock at the end 45 of each stroke. The vertical-arm has also an L-shaped piece 94 on its under edge, that projects under a so-called release-link 95 of flexible spring material. Said link has an aperture 96 on its front end, and is secured 50 to the armature 97 of one of the operating magnets 98 known as the release-magnet. Said armature is suspended from the frame by the supports 99, and is normally retained by the spring 100 away from the pole-piece 55 of the release-magnet. A stop is suitably provided behind said armature to limit its movement when retracted. The first-selector is provided with a peculiarly shaped mechanism 101 known as the double-dog. 60 It is pivoted so that it may swivel about a vertical axis that passes through the pivots 102. On its front side said double-dog has two dogs 103 and 104 so situated and constructed that the former may operate in 65 unison with the circular teeth 60, while the switch-shaft is raised and in normal rotary position, and so that the latter dog 104 may engage with the longitudinal teeth 59 when the shaft is rotated. To the right of the pivots 102 the body of the double-dog extends 70 rearwardly, and projecting down therefrom is an arm 105 that comes into play very prominently during the releasing of the switch. Near its extremity, and on the upper side of said body, a pin or lug 75 106 projects up. Said lug is normally caught in the aperture 96 of the release-link 95, and because of the action of the spring 100 through said link the dogs 103 and 104 are retained away from the shaft. Always, at 80 the first stroke of the vertical-armature, the link 95 is drawn away from the lug 106 by the piece 94, and then the double-dog is so rotated by the retracting-spring 107 that the dog 103 falls under the first circular 85 tooth, in order that when the vertical-armature returns to its normal position the said shaft will be retained by said dog in its new position. The release-link 95, while the double-dog is free, rests with its very end 90 upon the lug 106, out of locking engagement with it. When the vertical-magnet is energized a second time the shaft is raised a second step and the dog 103 at the second stroke passes from under the first tooth to 95 below the second tooth, holding the shaft again as above. The release-magnet 98 is composed of two coils like the vertical-magnet 85, but for simplicity only one coil is shown. If, while the shaft is raised, the 100 said release-magnet should be energized, the release-armature 97, of course, is attracted and the release-link 95 thrust forward to catch the lug 106 in the aperture 96. Upon the deenergization of the release-magnet the 105 retracting-spring 100 then withdraws the dogs 103 and 104 from the shaft, which latter, being deprived of its only support, then falls to normal position by its own weight. After the shaft is once raised it may be 110 rotated by a second operating magnet 108 known as the rotary-magnet. Said magnet has two coils 109 and 110 and, unlike the vertical-magnet, has its armature 115 pivoted in a vertical plane. Said armature may be moved about a vertical axis that passes through the pivots 112. The limit of the movement of said armature toward the rotary-magnet is determined by the pole-pieces of said magnet, which movement is produced by the rotary-magnet itself. The motion of the armature in the opposite direction is produced by the retracting-spring 113 and limited by a switch-stop behind the so-called rotary-arm 114. 120 This arm, like the vertical-arm, carries a so-called rotary-pawl 115. Similarly to the vertical-pawl, said rotary-pawl normally rests against a stop that retains it away from the longitudinal teeth, and when the 125 130

rotary-armature is attracted it is drawn into engagement with the longitudinal teeth by a spring 116 that is attached between the rotary-arm and the rear of said pawl. By the time that the rotary-armature strikes the pole-pieces of the rotary-magnet, the rotary-pawl also strikes a bumping post, as does the vertical pawl, and locks the shaft against any further advance by the force of its own momentum. At the end of the first rotary step the dog 104 falls behind the first longitudinal tooth, so that when the rotary-pawl falls back the shaft is retained. It should be evident that, as the shaft is rotated, the vertical-dog 103 is extricated from the groove in which it has been resting, by the passage of the rotary-dog 104 across the longitudinal tooth over which it has to slide at the time. But at the beginning of the rotation, it will be evident that the tooth which has been caught by the vertical-dog slides onto the shaft-rest 62, and in this way the shaft is still held raised after the rotation begins. The rotary-armature is not only provided with a so-called interrupter-finger 117 that separates the interrupter-springs 118 and 119 whenever the rotary-armature is attracted, but also with a rotary-armature-finger 120 that exercises certain controlling influences over the armature 121 of the last one of the operating magnets, namely the private-magnet 122. The said private-armature 121 works in a vibratory manner about a horizontal axis that passes through the supporting-points 123. This armature is formed with a forwardly-projecting arm 124, the latter having two flat surfaces in an approximately horizontal plane. Furthermore, the end of the said arm is bent at right angles downwardly and carries certain mechanical details, namely a lateral arm 125 which is designed to control circuits comprising the private-springs 126, 127 and 128, and a tooth escapement which includes two flexible springs 129 and 130, each of which springs is riveted by one end to the arm 124, one on the upper side and the other on the lower. The upper spring is straight and has formed on its end two tooth projections 131 and 132 which extend down, while the lower one is bent down and at right angles again to the front. This double angle on the lower spring is so designed that the latter may clear the bent portion of the private-arm, against which portion said spring rests with a degree of tension, and so that there may be space in front of said bent portion to receive two other tooth-shaped upwardly-projecting pieces 133 and 134 that are formed on the forward end of said escapement-spring 130, and which are sustained in juxtaposition to the upper teeth, but slightly to the rear thereof. A retracting-spring 135, suitably located, holds said armature normally away from the private-magnet pole-piece. A well-known auxiliary switching mechanism common to such switches is the so-called side-switch. It is shown in connection with the first-selector F¹ and comprises an arm 136 which is secured to the switch-frame in such a manner that it may be made to swivel in a vertical plane about the pivots 137. The right extremity of said arm is drawn out into a finger 138 that works in conjunction with the escapement-teeth previously described. Said teeth, in a manner to be described, convert the outward movement of the side-switch to a step-by-step motion, which movement is produced by a retracting-spring 139. At the base of the finger 138 a lug 140 is bent to the front and adapted to strike the cam 56 at a suitable time. Whenever the shaft is rotated, however, said cam is carried beyond the reach of said lug 85 and the finger 138 falls against the tooth 134. Near its left extremity the arm 136 carries a number of wipers 141, 142, 143 and 144, all suitably mounted upon a pin 145 and insulated therefrom and from each other. Said wipers are known as the side-switch-wipers and are adapted to be operated by the private-magnet and escapement device previously explained. If the private-magnet is energized once the private-armature is drawn down once and restored to its normal position. The escapement-finger 138 then passes from behind the tooth 133 onto the rear of the tooth 131, at the downward stroke of the private-armature 100 121, and from behind the latter tooth at the return stroke. As soon as the escapement-finger clears the latter tooth the retracting-spring 139 draws the side-switch to the second position where it is stopped by the lug 105 140 when it strikes the cam 56. Immediately, then, when the rotary-magnet energizes, the shaft is rotated and the cam passes away from the reach of the lug 140; and then the finger 138 of necessity falls against 110 the tooth 134, because of the tension in the spring 139. The rotation of the shaft results when the rotary-armature 111 is attracted by the rotary-magnet, and at the same time the rotary-armature-finger 120 115 depresses the private-armature 121 and causes the finger 138 to disengage from the tooth 134, and to advance against the tooth 132. Then, as the rotary-armature returns to normal position, and when the rotary-magnet deenergizes, the private-armature, on following the finger 120, permits the escapement-finger 138 to escape from the last tooth 132, thus permitting the side-switch to 120 pass to the third position with the said finger 138 resting against the side-switch-stop 146. In their normal positions the side-switch-wipers 141, 142, 143 and 144 engage with the contact-points 147, 148, 149 and 150, respectively. This position is known as 125 130

the first position of the side-switch, at which time it will be clear the finger 138 is held behind the escapement-tooth 133. In the second position, while the said finger is between the teeth 133 and 134, the said side-switch-wipers engage instead with the contact-points 151, 152, 153 and 154, respectively; and when the said finger 138 falls against the stop 146 the wipers change their positions into contact with contact-points 155, 156, 157 and 158, respectively. Between the pivots 137 and the wiper-supporting-pin 145 a rearwardly-extending arm 159 on the side-switch-arm 136 pivotally supports on its end one end of a link 160, the other end of which latter, being bifurcated, engages with the lower end of the double-dog-arm 105 which is constructed somewhat in the shape of an inverted T. Should the release-magnet be energized while the side-switch is in third position, and, of course, while the shaft is off-normal or rotated, the release-link 95, being attached to the release-armature 97, is thrust forward when the release-armature is attracted, and catches the lug 106 in the aperture 96. Then when said release-armature is restored the spring 100, as before described, withdraws the dog 103 from the circular teeth 60. At the same time the arm 105 drives the link 160 back, which latter then rotates the side-switch-arm 136 about the pivots 137 against the tension of the side-switch retracting-spring 139, and thus drives the finger 138 along between the springs 129 and 130 to a position behind the tooth 133, locking the side-switch in the first or normal position. The switch-shaft being unlocked by the removal of the dog-support 104, and being thus left free is rotated by the coil-spring 65 until the instant that the end of the shaft-rest enters the slot 61, at which time the shaft drops to its normal position. Therefore, after the switch has been operated, the energization and deenergization of the release-magnet is sufficient to restore the switch completely to its normal position. The line and private banks are each provided with ten rows of contact-terminals, each row consisting of ten sets of contacts. Therefore, the shaft is so constructed that it may be raised to any one of ten levels; at each level it may be rotated ten successive steps in order that the wipers which it carries may be placed in connection with any one of the terminals of the ten sets of contact-terminals in each level. The repeater R comprises two line-relays 200 and 201 which, through their respective armatures 202 and 203, operate between them the line-relay-springs 204, 205 and 206 and the two release-springs 207 and 208. A differential-relay 209 has two windings 210 and 211 one of which is connected through the vertical-line-relay 200 with the vertical side of the main talking conductors, while the other end of said winding 210 is permanently connected with the non-grounded terminal of battery B. The second winding 211 is connected through the rotary-line-relay 201 to the rotary side of the main talking conductors, while its other end is connected with a spring 212 of a so-called pole-changing-relay 213. Said spring is normally connected with a second spring 214 that is permanently connected with the non-grounded terminal of battery B'; but it may be switched by the armature 215 of the relay away from said spring 214 and into contact with a third and grounded spring 216. With such construction the differential-coil 210 may be energized only when the vertical side of the line is grounded, but the other coil 211 may be energized when the rotary side of the line is grounded, or at times when the spring 212 is grounded. In one case the current will flow in one direction, and in the other in the opposite direction, so that the two coils may be energized to neutralize or reinforce each other, depending upon the direction in which the current through the latter coil 211 is made to flow. Also, with the arrangement described, the two ends of the coil 211 may be grounded, rendering said coil or winding 211 short-circuited through ground for the purposes herein set forth. Said differential-relay, when energized, has the power through its armature 217 to separate the springs 218 and 219 and to close the springs 220 and 221. The former rest normally in contact, and the latter out of contact. In addition, the repeater has another relay 222—an auxiliary-relay—the office of which is to maintain the springs 223 and 224 separated from the springs 225 and 226, respectively, whenever it is energized. The repeater has also two repeating-coils 227 and 228, the former with two windings 229 and 230, and the latter with two windings 231 and 232. Said coils are separated by the condensers 233 and 234. Of course, the different relays pointed out are mounted rigidly with respect to the springs associated with them, but they may be mounted and arranged on any suitable base and in any suitable manner. A dead-resistance-coil 235 of about 60 ohms is also included in the repeater for purposes hereinafter disclosed.

The second-selector S employed with my system is identical with the first-selector F. However, parts like the springs 66, 67 and 68 and the bridge-cut-off-relay 76 are removed altogether. Furthermore, conductors like the ones that terminate in the bridge-cut-off-relay-springs 78, 79 and 80 are permanently united and the springs discarded.

Fig. 4 shows the connector C which has many parts and circuits very similar to those

of the first-selector. The line and private banks 250 and 251 will be recognized. The switch-shaft 252 is identical with the first-selector-shaft and is, therefore, provided 5 with the line-wipers 253 and 254, the private-wiper 255, the cam 256, longitudinal and circular teeth 257 and 258, respectively, the normal-post-arm 259, and the coil-spring 260. The vertical movement of the shaft is, 10 of course, produced by means of the vertical-magnet 261, vertical-arm 262, and vertical-pawl 263, the said vertical-arm 262 being supplied with the L-shaped piece 264, as usual. The release-magnet 265, however, 15 has its armature 266 on the right side instead of on the left side, which armature is constructed with an elongated front extremity 267 that reaches as far as the middle section of the body of the double-dog 268. The 20 release-link 269 is under the control of the L-shaped piece 264, and is permanently secured to the switch-frame at the pin 270. The double-dog has the usual vertical and rotary locking-dogs 271 and 272, respectively, 25 and the side-switch releasing-arm 273, while on the upper side of the body of the double-dog the lug 274 that is caught by the release-link 269 is in its usual position. When the release-magnet of the connector is 30 energized the release-link 269, instead of being thrust forward to catch the said lug 274, remains where it is and, instead, the double-dog 268 is struck by the armature 266 at a point to the right of the bearings 35 275 by the end 267, so that the lug 274 is driven under the aperture 276 in which latter it is caught by the release-link 269. The double-dog 268 is thus prevented from returning to its operative position when the 40 release-magnet becomes deenergized. The rotary-magnet 277 has a rotary-armature 278 that is quite simple. This latter is provided with only a vertical-arm 279 upon the extremity of which the rotary-pawl 280 is 45 located. The rotation of the shaft is produced in the same mechanical manner described in connection with the first-selector, each time that the rotary-magnet is energized. The private-magnet 281, the private- 50 armature 282, springs 283 and 284, escapement-teeth 285, 286, 287 and 288 and the arm 289 are identical with the similar parts of the first-selector. The said arm 289, however, controls the private-springs 290, 291, 55 292 and 293, so that when the private-armature 282 is down the first two of said springs are separated and the last two brought into contact, and when the said armature is up the reverse takes place—that is, the springs 60 290 and 291 close and the springs 292 and 293 separate. In the side-switch of the connector the side-switch-arm 294, escapement-finger 295, cam-lug 296, side-switch-stop 297, and retracting-spring 298, on one side of the 65 pivots 299, are similar to like parts of the

first-selector side-switch; while the member 800, link 301, side-switch-wipers 302, 303, 304 and 305 together with their corresponding contact-points 306, 307 and 308; 309, 310 and 311; 312, 313 and 314; and 315, 316 and 70 317 are on the other side of said pivots. Among the relays of the connector the vertical-line-relay 318, by its armature 319, can flex the spring 320 against the ground-spring 321, and the spring 322 toward the 75 spring 323, when said relay is magnetized. The rotary-line-relay 324, in the same manner, by its armature 325, when the relay is magnetized, forces the spring 326 against the same ground-spring 321, and permits the 80 spring 323 in turn to bend toward the former spring 322. Said two springs 322 and 323 are so adjusted that they come into contact with each other whenever the two armatures 319 and 325 are attracted at the same time. 85 The ringer-relay 199 is a feature common to all connectors of the type under consideration and can, when magnetized, open the connection between the called and the calling line and place across the former the terminals of the ringer-generator J. This operation is accomplished by means of the armature 327 and the ringer-relay-springs 328, 329, 330, 331 and 332. In addition, the connector has two double-wound relays 333 and 334, known as the front and back bridge-relays, the former being differentially wound. Each of these coils comprises two windings 335 and 336, and 337 and 338, respectively. The differential-relay has its 90 windings 335 and 336, respectively, connected with the vertical and rotary line-relays 318 and 324, and through these relays said windings are connected with the main line talking conductors, as will be more 95 clearly pointed out, and said differential-relay, by its armature 339, and when energized, forces the differential-relay-spring 340 from the spring 341 against which latter it 100 normally rests and into contact with the third differential-relay-spring 342. Furthermore, the winding 335 is connected permanently with the vertical line relay 318 between the vertical-line-conductor and the non-grounded terminal of the battery, and is 105 subject to energization only when the vertical-line-conductor is grounded; but the winding 336, while permanently connected with the rotary-line-conductor through the rotary-line-relay 324, by one end, has its 110 other terminal connected with the back-bridge-relay-spring 343. This latter spring, when the back-bridge-relay 334 becomes energized, is forced away from its normally 115 engaging spring 344 into engagement with the spring 345, which latter spring is connected to ground each time that the connector side-switch-wiper 303 passes to third position. The spring 344 with which the spring 343 normally engages, it should be noticed, 120 125 130

is permanently connected to the non-grounded pole of the battery. With such arrangement, the differential-relay 333 may be energized whenever the vertical or rotary side of 5 the main calling line is grounded, after said line has been trunked to the connector, or may also become energized if both of said line-conductors are grounded at the same time. In the latter case, the coils 335 and 10 336 reinforce or augment each other with their magnetic influences; but if the back-bridge-relay 334, after a line is called, should be energized while the main line-conductors of a calling line are connected through the 15 repeater, as will be shown, or if they meet in any way whatever, an electric current will then pass from the side-switch-wiper 303 through the differential-winding 336 to the rotary side of the line and on to the vertical 20 side, then through the winding 335 to the non-grounded terminal of the battery, in which case the differential-relay is not energized. The windings 337 and 338 of the back-bridge-relay 334 are connected one with 25 the vertical side of the main line and the other with the rotary side of the main line. The other end of the first coil 337 is connected to the differential-relay-spring 341, which latter normally is found in electrical 30 contact with the middle differential-relay-spring 340 that constitutes the non-grounded terminal of the battery. The other terminal of the winding 338 is permanently connected with the side-switch-wiper 303, which latter, 35 when in the third position, is connected with ground. Therefore, when the main line-conductors are connected through the called sub-station, a current will flow from the side-switch-wiper 303 through the winding 40 338 of the back-bridge-relay to the rotary side of the main line, then to the vertical side and back through the second winding 337 to the non-grounded terminal of the battery. These windings, unlike the windings 45 of the differential-relays, when the main lines are thus connected, reinforce or augment each other to energize the back-bridge-relay. The release of the first-selector, in a manner already clearly described, does not 50 occur until the deenergizing of the release-magnet of the first-selector, but the release of the connector, as plainly set forth, occurs immediately upon the energizing of its release-magnet. Should the connector-shaft 55 252 be in a raised condition when the release-magnet 265 is energized, the release-armature 266, as previously stated, then moves the double-dog 268 under the release-link 269, which latter then catches the lug 274 and 60 holds said double-dog out of engagement with the shaft. Said shaft then being free returns, for the same reasons described in connection with the first-selector-shaft, to its normal or released condition. The normal- 65 post-arm 259 of the connector has control of

two springs 197 and 198 which are closed when the shaft is raised, and open when it is down.

In Fig. 2 the first-selector F^2 that is associated with the called line is identical with the first-selector F^1 of the calling line, and needs no explanation, since like parts are likewise represented. When reference is made to the parts of said called first-selector it will be understood that their functions and constructions are the same as those already described for the first-selector F^1 . In the system under consideration, of course, it is clear that there may be a multiplicity of sub-stations common to the central stations, 70 each of which is connected with the central station by a line composed of two conductors, each of which lines has permanently allotted to it a first-selector. The first-selectors may be sub-divided into groups of 75 one hundred, each with all corresponding line-bank-terminals of a given group connected in multiple, and a similar arrangement being followed in connection with the private-bank-terminals. For each level of 80 first-selector-line-bank-terminals ten trunk-lines are provided which terminate in suitable switches arranged in groups. Therefore, for each level to which a first-selector-shaft may be raised, the line-wipers are 85 placed on a level with a different set of switches one of which may be selected for the purpose of reaching subscribers in different numerical groups. Each first-selector is connected with a given set of bank-contact- 90 points in the banks of the connectors of the hundred to which said first-selector belongs, and when the first-selector comes into use a guarding potential is placed at the connector-private-bank-contacts of the line of 95 100 the calling first-selector to prevent any calling subscriber from calling-in on said line over the so-called normal-trunk-conductors that extend between the connector-banks and the first-selector. 105

To more fully understand the operations and circuits in connection with my invention, a description will now be given of the apparatus and circuits brought into use 110 in the system when one subscriber calls another subscriber, as illustrated in Figs. 1 and 2. For example, when the subscriber at sub-station #7000 calls the subscriber at sub-station #2420, the subscriber at the calling sub-station #7000 removes his receiver from the switch-hook 2 and causes the ground-springs 23 and 24 to come into contact and complete a circuit between the ground-terminal G^3 and the conductors 400 and 401. Then the vertical-push-button 29 115 120 is pressed twice, and the rotary-button 30 once, again the first button 29 four times, and the second button 30 once, then the button 29 twice, and the button 30 once, and for the last time the first button ten times, 125 130

and the last button once. When the spring 33 is forced onto the ground-post 22 twice in succession for the first time, the vertical-line-conductor 402 is grounded twice, causing the vertical-line-relay 69 of the first-selector to become magnetized and attract its armature 71 twice. The energizing current that passes through said vertical-line-relay at the time enters the line at the 10 ground-terminal G³, then passes to the ground-post 22, and through the spring 33 to the vertical-line-conductor 402, thence through the vertical-side-switch-wiper 143, conductor 404, vertical-line-relay 69, conductor 405, bridge-cut-off-relay-springs 79 and 80, conductors 406, 407 and 408 to the non-grounded terminal of battery B¹ and to ground G¹. As a result, the line-relay-spring 73 is forced onto the ground-spring 20 75 twice, which operation closes a second energizing circuit through the vertical-magnet 85. The current in this second circuit enters the line at the ground-terminal G⁴ and then passes through the springs 75 and 25 73 to the conductor 409, and through the private-springs 127 and 126 and conductor 410 to the vertical-magnet 85, passing thence through the conductors 411, 412, 413 and 408 to the non-grounded terminal of 30 battery B¹ and to ground G¹. The vertical-magnet 85 then attracts the vertical-armature 86 twice and raises the switch-shaft two steps. At the first step, of course, the release-link 95 is withdrawn from the 35 double-dog 101, at which time the dog 103 engages with the circular teeth 60 and prevents the shaft from falling to its original position. So soon as the switch-shaft rises, the off-normal-spring 66 then closes with 40 the grounded contact-point 68, at which instant and by which act the connector-private-bank-contacts that correspond to the line-conductors of the sub-station #7000 are connected with ground G⁵, which connection establishes a guarding potential for 45 the line #7000, so that no subscriber may be able to connect with it after once the first-selector F¹ of said line has been operated. After the vertical-line-conductor is grounded twice the rotary-line-conductor 414 is 50 grounded once through the spring 34. An electric current then flows through the rotary-line-relay 70 for a moment, which magnetizes the said rotary-line-relay, causing the latter to attract its armature 72 once and force the spring 74 once against the ground-spring 75. The current then passes from G³ to the ground-post 22, thence through the spring 34 to the rotary-line-conductor 414, side-switch-wiper 144, contact-point 150, conductor 415, rotary-line-relay 70, conductor 416, springs 78, 79 and 80 to the non-grounded terminal of battery B¹ and to ground G¹. When the springs 74 55 and 75 close together a second magnetizing

circuit is completed through the private-magnet 122. The electric current in this case flows from the grounded terminal G⁴ through the line-relay-springs 75 and 74, conductors 417 and 418 to the private-magnet 70 122, after passing through which it passes through the conductors 419, 413 and 408 to the non-grounded terminal of battery B¹ and to ground G¹. The private-armature 121 being attracted once and restored immediately, the escapement-tooth 133 first clears the escapement-finger 138, which latter then falls against the second tooth 131, and when the armature returns to its normal position this latter tooth also 75 disengages the said escapement-finger. At that instant, the side-switch is drawn into the second position by the retracting-spring 139, with the cam-lug 140 resting against the cam 56. It will be understood that the 80 prongs of the bifurcated end of the link 160, that rest upon the T-shaped extremity of the double-dog releasing-arm 105, are of sufficient length to permit the said releasing-arm 105 to move from the position that 85 it holds when the double-dog is held normally locked by the release-link 95, to the position it assumes when the said double-dog is released, without disengaging from 90 said prongs. At the moment that the side-switch passes from the first to second position a circuit is completed through the rotary-magnet 108 when the side switch-wiper 141 closes with the contact-point 151. The current then flows from the ground 100 terminal G⁶ to the contact-point 151, through the side-switch-wiper 141 and conductor 420 to the rotary-magnet-coil 110, thence through the interrupter-springs 118 and 119 and through the second rotary-magnet-coil 109 to the conductors 412, 413 and 408 to the non-grounded terminal of 105 battery B¹ and to ground G¹. The rotary-magnet 108 then attracts the rotary-armature 111 and forces the rotary-pawl 115 into 110 engagement with one of the longitudinal teeth 59 causing the shaft to rotate one step. Just at the time, or at the instant before the rotary-armature strikes the rotary-magnet pole-pieces, the rotary-dog 104 falls behind the first of the longitudinal teeth, in the manner already described, to 115 prevent the shaft from returning to its normal position when the rotary-magnet becomes deenergized at the instant that the 120 interrupter-finger forces the interrupter-springs apart and destroys the energizing circuit through the said magnet. This interruption occurs just at the time when the rotary-armature strikes the pole-pieces, or 125 an instant later. When the rotary-pawl 115 advances to engage the longitudinal teeth, as described, the rotary-armature-finger comes into contact with the private-armature 121, producing a depression of the 130

latter at the same time that the rotary-pawl produces a rotation of the shaft. As the shaft begins to rotate, the cam 56 very soon passes out of reach of the cam-lug 5 140 and permits the escapement-finger 138 to fall against the tooth 134 before the rotary-armature-finger 120 has depressed the private-armature 121 too far. Very soon, however, the said tooth 134 is carried below the finger 138, which latter then falls 10 against the upper tooth 132 just at about the time that the shaft-wipers are rotated onto the first contact of the second level of their respective banks. As soon as the 15 energizing circuit through the rotary-magnet is interrupted, the rotary-armature then begins to return to its normal position, and the private-armature 121 as well, following up the receding movement of the rotary- 20 armature-finger 120. Very soon the tooth 132 disengages the escapement-finger 138 also, and the side-switch springs into third position with the escapement-finger 138 against the side-switch-stop 146. The shifting 25 of the side-switch takes place just before the interrupter-finger permits the interrupter-springs 118 and 119 to reengage, so that by the time that they do reengage the energizing circuit that has been described 30 through the rotary-magnet has been destroyed between the side-switch-wiper 141 and the contact-point 151. When the motion of the rotary-armature ceases permanently the operation of the first-selector 35 comes to an end, the line-wipers 53 and 54 having seized upon an idle trunk-line similar to the trunk-line the conductors 421 and 422 of which terminate at the tenth set of contacts of the second level of the same 40 line-bank. The seized line is protected from further seizure by a guarding potential at the private-wiper, and, therefore, at the first contact of the second level of the private-bank 51, and to all other private- 45 contacts in multiple. Said guarding potential is established by reason of the connection between the grounded terminal of battery B^1 and said private-contacts, through the ground terminal G^1 , side-switch-wiper 50 142, conductor 423, back-release-relay 81, conductor 424, and the private-wiper 55. Similarly, should any first-selector appropriate to its use the second trunk-line of the same level a guarding potential will 55 appear at the second private-contact of the second level of the private-bank 51, as well as at all other private-banks in multiple. And should a third first-selector seize the third trunk on the same level a guarding 60 potential will appear also at the third private-contact of the second level, and should the fourth, fifth, etc., and ninth trunks be occupied, guarding potentials would be found at the fourth, fifth, 65 etc., as well as at the ninth, private-contact terminals of the second level of the private-bank. Therefore, if the first nine trunk-lines of the second level are busy a guarding potential is found at each one of the first nine private-contacts of the second level of the private-bank 51. If this condition exists at the time that the calling subscriber grounds his rotary-line-conductor by pressing button 30, the rotation of the shaft will not terminate as soon as the wipers have 70 moved onto the first terminal of the level to which they have been raised. The first nine private-contacts being grounded, then when the calling subscriber grounds the rotary side of the line the side-switch trips into second position in the manner described; but then the rotation of the shaft will begin, not to cease, until the wipers have been carried beyond the last of the busy trunk-lines—in this case onto the tenth terminal of the second level of the banks in question. This operation takes place in the following manner: The energizing circuit through the rotary-magnet being closed, as was pointed out, at the juncture when the side-switch-wiper 141 engages with the contact-point 151, the rotary-armature is attracted by the rotary-magnet 108, and the shaft is rotated one step in the manner described, so that the line and private wipers are rotated into engagement with the first terminal of the second level of their respective banks. At the same time the private-armature is depressed by the rotary-armature-finger and the interrupter-springs 118 and 119, are, at the end 90 of the stroke, separated by the interrupter-finger 117. There being a guarding potential at the first contact which the private-wiper meets, a circuit is completed through the private-magnet 122, which extends from the grounded terminal of the battery B^1 through the private-wiper of whatever first-selector is occupying the first trunk of the second level in question, through the bank-multiplying conductors to the contact-point with 95 which the private-wiper 55 has engaged, thence through said private-wiper 55, conductor 424, winding of the back-release-relay 81, conductor 423, side-switch-wiper 142, contact-point 152, conductors 403 and 418 100 and private-magnet 122 to the non-grounded terminal of battery B^1 and to ground G^1 . The private-armature is thereby retained in the depressed condition even after the energizing circuit is broken at the interrupter-springs, and while the rotary-armature-finger 120 returns to its normal position in response to the retracting tension of the rotary-armature retracting-spring 113, since the escapement-finger 138 is held by the upper foremost escapement-tooth 132. The side-switch-wiper 141 being, therefore, retained in engagement with the grounded contact-point 151, as soon as the interrupter-springs reengage the energizing circuit 105 115 120 125 130

through the rotary-magnet 108 is completed once more. As a result, the rotary-armature is attracted again, the shaft is rotated one more step, and the private-wiper 55 is moved 5 onto the second terminal of the second level of the private-bank 51. Said second contact also being grounded, it follows that the energizing circuit through the private-magnet is still maintained, so that the side-switch is 10 still not liberated when the rotary-armature again returns to its normal position. Clearly, then, the shaft will be rotated in a step-by-step manner as long as the private-wiper continues to meet with grounded private- 15 contacts. After having rotated onto the ninth contact, the private-wiper is rotated one more step into engagement with the tenth contact of the second level of the private-bank; but this last contact being de- 20 void of guarding potential, as soon as the said wiper leaves the ninth contact, the magnetizing circuit that has, up to this time, maintained the private-magnet energized is broken. This occurs at just about 25 the time when the rotary-armature is at the end of its attractive stroke; so that the private-armature that has, up to this time, held the side-switch in its second position through the magnetizing force that has now 30 disappeared from the private-magnet, falls back upon the rotary-armature-finger and follows said finger as the rotary-armature returns to its normal position. Between the time that the private-armature is released 35 by the private-magnet and the time that the rotary-armature fully regains its normal position, the escapement-finger 138 which, during the rotation of the shaft, has been resting against the foremost tooth of the upper 40 escapement-spring, disengages from said tooth and permits the side-switch to pass into the third position. It is then that the side-switch-wiper 141 leaves the contact-point 151 and passes onto the contact-point 45 155. This disengagement occurs just before the interrupter-springs 118 and 119 reengage, so that the circuit through the rotary-magnet is permanently broken in order that no further rotation of the shaft may take 50 place during its use. The side-switch-wipers 143 and 144 having engaged with the contact-points 157 and 158, the subscriber's line-conductors 402 and 414 are then extended through the respective wipers and over 55 the conductors 425 and 426 to the vertical and rotary line-wipers 53 and 54, respectively. Said wipers being at the time in engagement with the tenth contact of the second level of the line-bank the calling sub- 60 scriber is thus placed in connection with the repeater R. It may be stated at this point that if, after the subscriber has begun to call, and before the first-selector has trunked to the repeater, he should desire to discon- 65 tinue his call he may interrupt the opera-

tion of the first-selector and restore it by simply hanging up his receiver on the switch-hook 2. This may occur while the side-switch is either in the first or second position, it matters not. As a result of restoring the receiver, both sides of the main line will be grounded simultaneously. The rotary and vertical line-relays 70 and 69 will be magnetized at the same time, and as a result the release-magnet 98 of the first- 70 selector will be energized and the first-selector will be restored. It has been described that in its action the release-cam-arm 3, as it passes down, when the receiver is restored, flexes the release-springs 25, 26 75 and 27 into contact for a moment. Of these springs the release-springs 25 and 26 are connected, respectively, with the vertical and rotary line-conductors, while the third release-spring 27 is connected to ground G³. 80 Therefore, as a natural result, the temporary engagement of these three springs sends a ground impulse over each side of the main line, with the effect upon the first-selector-line-relays already mentioned. The current 85 through the vertical-line-relay, during the release, passes from ground G³ through the ground-springs 24 and 23, conductor 400, release-springs 27, 26 and 25, to the vertical-line-conductor 402, and thence through said 90 relay to the non-grounded terminal of battery B¹ and to ground G¹. Through the rotary-line-relay 70 the current flows from the same ground G³ to the release-spring 27, thence through the release-spring 26 to the 95 vertical-line-conductor 414, thence through the line-relay in question to the non-grounded terminal of battery B¹ and to ground G¹. Since the contact-points 149 and 153 associated with the vertical-side-switch-wiper 143 100 are connected together, and since the contact-points 150 and 154 of the rotary-side-switch-wiper 144 are connected together, it will be evident that it makes no difference for a release whether the side-switch is in 105 first or second position, as the energizing circuits during the release, as pointed out in the conditions under consideration, will be the same. The fact is already familiar that when the rotary-line-relay is energized 110 the private-magnet 122 is energized, as a result of which the latter, during its energization, maintains the private-springs 127 and 128 in contact. It is also familiar that when the vertical-line-relay is magnetized 115 the private-spring 127 is connected with ground G⁴ at the line-relay-springs. It was shown that when said private-spring 127 was grounded, and while in contact with the spring 126, that the vertical-magnet 85 was 120 energized; but in this case, since said springs 127 and 126 are not in contact, but instead the springs 127 and 128 are in engagement, a different circuit is established that comprises the release-magnet 98. The energiz- 125 130

ing current in this circuit passes from the ground G^4 to the private-springs 127 and 128, thence through the conductors 427 and 428 and the release-magnet 98, conductors 5 411, 412, 413 and 408 to the non-grounded terminal of battery B^1 and to ground G^1 . When the cam-arm 3 disengages the release-springs, the line-relays 69 and 70 then become deenergized, and as a result the release-magnet 98 becomes deenergized and the armature of the latter, in regaining its normal position, restores the first-selector-switch in a well-known manner. It should be made clear that when the first-selector-shaft is first operated, and when the off-normal-spring 66 closes into electrical contact with the contact-point 68, a guarding potential is then established at the connector-private-bank-contacts, through the so-called private-normal-conductor 429. The establishment of this guarding potential is for the purpose of preventing any other calling subscriber from attaining connection with the line #7000 over the normal-line-conductors 430 and 431 that terminate in the connector-banks, while the said line is making the call. But when the shaft falls to its normal position, when the switch is released, this guarding potential is destroyed at the instant that the normal-post-arm 63 forces apart the springs 68 and 66. However, since the subscriber continues his call instead of releasing the then, after pressing the push-button 29 twice and the push-button 30 once, continues by pressing the push-button 29 again four times. Again the vertical-line-conductor 402 is grounded four times momentarily. The first-selector-line-relays 69 and 70 having been cut off of the line at the instant that its side-switch passes into third position, and the line being connected then with the repeater R, the grounding of the vertical-line-conductor energizes the line-relay 200 and the differential-relay 209 of the repeater R. The current in this case, after reaching the vertical-line-conductor and the vertical-side-switch-wiper 143 of the first-selector, passes thence through the contact-point 157, conductor 425, the vertical-line-wiper 52, trunk-conductor 421, conductor 432, line-relay 200, conductor 433, winding 210 of the differential relay 209, conductors 434, 435 and 436 to the non-grounded terminal of battery B^1 55 and to ground G^1 . The energization of the line-relay 200 causes the spring 204 to be pressed onto the spring 205, while the energization of the differential-relay forces the springs 218 and 219 apart and closes the springs 221 and 220. The line-relay-spring 204, being connected directly with the inter-exchange trunk-conductor 437, through the conductor 438, and the spring 205 being connected to ground G^8 , the engagement of the 60 springs 204 and 205 therefore connects the said trunk-conductor 437 with ground. Since the said relay 200 is energized four times, the said trunk-conductor becomes grounded four times. The object in separating the springs 218 and 219 at the same time that the trunk-conductor 437 is grounded is to prevent the ground impulses to said trunk-conductor from being conducted to the rotary-trunk-conductor 439. The circuit through which the vertical-trunk-conductor 75 437 reaches the ground terminal G^8 extends from said trunk-conductor through the conductor 438, springs 204 and 205, conductor 440, springs 224 and 226, to the ground terminal G^8 . This ground connection would 80 reach the rotary-trunk-conductor 439 through the pole-changing-relay 213, conductors 441 and 442, springs 218 and 219, conductor 443 to the rotary-trunk-conductor 439, were it not that the springs 218 and 219 85 are kept apart. The results produced by grounding the vertical-trunk-conductor 437 will be described herein. After the vertical-button 29 has been operated as described, the rotary-button 30 is operated once. The 90 latter, as a result, connects the rotary-line-conductor 414 to ground for a moment. In this case, the rotary-line-relay 201 and the differential-relay 209 of the repeater R are energized simultaneously by a current flowing from the ground G^3 to the rotary-line-conductor 414, and to the side-switch-wiper 144, thence to the contact-point 158, conductor 426, rotary-line-wiper 54, trunk-conductor 422, conductor 444, rotary-line-relay 201, 100 conductor 445, winding 211 of the differential-relay 209, conductors 446 and 447, springs 212 and 214, conductor 448 to the non-grounded terminal of battery B^1 and to ground G^1 . The energizing of the differential-relay 105 actuates the springs under its control as before, while at the same time the rotary-line-relay 201 forces the springs 205 and 206 into contact, and thereby grounds the rotary-trunk-conductor 439. The connection between ground and said trunk-conductor 439 is made from the ground-terminal G^8 through the springs 226 and 224, conductor 440, springs 205 and 206, conductor 449, springs 223 and 225 and conductor 450 115 to the said trunk-conductor 439. The separation of the said springs 218 and 219 by the differential-relay 209 prevents the vertical-trunk-conductor 437 from being grounded together with the rotary-trunk-conductor 120 439, at this time. The engagement of the springs 221 and 220, each time that the differential-relay 209 has been energized heretofore, plays no part, and is of no significance, save during a release which will be 125 described. After the first-selector F¹ has trunked to the repeater R, the switches may be released again at this point of the calling operation by restoring the receiver to the switch-hook. The simultaneous grounding 130

of the vertical and rotary line-conductors will produce a simultaneous energization of the vertical and rotary line-relays 200 and 201 over circuits that need not be further described. The windings of the differential-relay 209 are so arranged that when the line-conductors are grounded current passes through them in such a direction that the said windings reinforce or augment each other magnetically, and, therefore, the said differential-relay becomes energized at the same time that the line-relays 200 and 201 become energized. This being the case, the differential-relay-springs 221 and 220 are brought into contact at the same time that the repeater trunk-release-springs 207 and 208 are forced together by the simultaneous energization of the said relays. The simultaneous engagement of said two sets of springs establishes an energizing circuit that includes the first-selector-back-release-relay 81. The current in this circuit flows from the ground terminal G^7 of the first-selector-side-switch, thence to the contact-point 156 and through the side-switch-wiper 142, conductor 423, through the back-release-relay 81, conductor 424, private-wiper 55, release-trunk-conductor 451, trunk-release-springs 207 and 208 of the repeater R, conductor 452, resistance-coil 235, springs 221 and 220, conductors 435 and 436 to the non-grounded terminal of battery B^1 and to ground G^1 . The back-release-relay 81, upon being energized, forces the springs 83 and 84 into electrical contact, and thus in turn a second circuit including the release-magnet 98 of the first-selector is completed. This circuit extends from the ground terminal G^9 through the springs 83 and 84, conductors 453 and 428, release-magnet 98 to the non-grounded terminal of battery B^1 and to ground G^1 . As soon as the release-springs at the substation #7000 disengage, the current through the repeater-line-relays 200 and 201 and the differential-relay 209 is interrupted, and the energizing circuit through the back-release-relay 81 is opened at the differential-relay-springs 221 and 220, and at the release-springs 207 and 208. The back-release-relay 81, on becoming deenergized, destroys the energizing circuit through the release-magnet 98 which at once permits its armature 97 to return to normal position and produce the release of the first-selector. It should be noted that when the line-relays 200 and 201 are energized during the release, under these conditions, the vertical and rotary trunk-conductors 437 and 439 are simultaneously grounded when the springs 204 and 206 are forced onto the spring 205. The subscriber not wishing to release, however, continues his call; but before proceeding, the effect of grounding the trunk-conductors 437 and 439 will be considered.

Since the said trunk-conductors are directly

connected with the second-selector S in the same manner that the line-conductors 402 and 414 of the sub-station #7000 are connected with the first-selector F¹, the grounding of said trunk-conductors, as described, 70 results in the operation of the second-selector in the identical manner in which the first-selector F¹ is operated when the buttons 29 and 30 are pressed. The grounding of the vertical-trunk-conductor 437 energizes the 75 vertical-line-relay 164, and the current flows from the ground terminal G^8 to the vertical-trunk-conductor 437, as stated, over which it flows to the side-switch-wiper 165, contact 166, and through the conductor 454, vertical-line-relay 164, conductors 455, 456 and 457, to the non-grounded terminal of battery B^2 and to ground G^2 . The line-relay-springs 167 and 168 are forced together in the usual manner, and a circuit through the 80 vertical-magnet 169 is established that permits a flow of current from the ground terminal G^{10} through the springs 168 and 167, conductor 458, private-springs 170 and 171, vertical-magnet 169 to the non-grounded 85 terminal of battery B^2 and to ground G^2 . The resulting energization of the vertical-line-relay four times causes the vertical-magnet 169 to become energized four times, and as a result the switch-shaft is raised 90 four steps in a manner that needs no explanation. At the end of this operation, of course, the switch-wipers 173, 174 and 175 will be found opposite the first contact of the fourth level of their respective banks. 95 The grounding of the rotary-trunk-conductor 439, following the grounding of the vertical-trunk-conductor 437, produces an operation of the rotary-line-relay 178. The current in this case, after reaching the rotary-trunk-conductor 439 from the ground terminal G^8 , as described, passes on to the side-switch-wiper 179, contact-point 180, conductor 459, rotary-line-relay 178 to the non-grounded terminal of battery B^2 and to 100 ground G^2 . This relay, being energized momentarily, energizes as a result the private-magnet 181 once at the instant that the springs 182 and 168 are forced into contact. The current here flows from ground G^{10} 115 through the springs 168 and 182, conductors 460 and 461, private-magnet 181 to the non-grounded terminal of battery B^2 to ground G^2 . The private-magnet, by actuating its private-armature once, permits the side-switch to pass into second position, at which time the side-switch-wiper 183 passes from engagement with the contact-point 184 onto the grounded contact-point 185. The union of said side-switch-wiper with the said 120 grounded contact-point produces an actuation of the rotary-magnet 186 by means of the current that flows from the ground terminal G^{11} to the contact-point 185, thence through side-switch-wiper 183, 125 130

conductor 462, rotary-magnet 186 to the non-grounded terminal of battery B² and to ground G². Assuming that the first nine trunks of the fourth level of the second-
 5 selector S are busy, the rotation of the shaft, in a manner clearly described in connection with the first-selector F¹, continues until the shaft has been rotated ten steps, placing the switch-wipers in connection with the tenth
 10 terminal of the fourth level of the banks. Of course, the private-magnet during the rotation of the private-wiper over the busy contacts is maintained energized, as was described in connection with the first-selector.
 15 The current here passes naturally from the busy contacts to the private-wiper 175, through the back-release-relay 187 to the side-switch-wiper 188, which latter, being in second position, extends the circuit through
 20 the contact-point 189 and through the private-magnet 181 to the non-grounded terminal of battery B² and to ground G². The line-wipers 173 and 174 are then, of course, in electrical connection with the trunk-con-
 25 ductors 463 and 464, and the private-wiper 175 in engagement with the release-trunk-conductor 465. The side-switch-wiper 188, while in third position, being connected to ground G¹² through the contact-point 190,
 30 the usual guarding potential is supplied to the private-wiper 175, and as a result to the private-contact with which it is connected, in order that no other trunk-seeking second-selector may be able to seize upon the
 35 trunk-line-conductors 463 and 464. The second-selector S, of course, may be released if the trunk-conductors 437 and 439 are grounded simultaneously while the side-
 switch is in the first or second position, in
 40 the same manner that the first-selector is released, when both sides of the main line are grounded. This will occur, as has been pointed out, if the calling subscriber hangs up his receiver at that stage of the call when
 45 the said second-selector-side-switch is in first or second position. It will be clear that if the vertical and rotary line-conductors 402 and 414 are grounded simultaneously while the first-selector, repeater and
 50 second-selector are connected, and while the second-selector-side-switch is either in first or second position, the first-selector will be released as described, during which release the trunk-conductors 437 and 439 will be
 55 grounded simultaneously, producing at the same time a release of the second-selector. The switching of the second-selector onto the trunk-conductors named places the sub-
 station #7000 in direct communication with
 60 the connector C, which latter will in turn be operated when the calling subscriber next presses his button 29 twice. The grounding of the vertical-line-conductor will cause the vertical-line-relay 200 and the differen-
 65 tial-relay 209 of the repeater R to be ener-
 gized twice. As a result, the vertical-trunk-conductor 437 becomes grounded twice; and said trunk-conductor having been connected through to the connector C, it is evident that the vertical-line-relay 318 and the dif-
 70 ferential-relay 333 of the latter will be en-
 ergized twice by a current flowing from the ground terminal G³ at the repeater to the vertical-trunk-conductor 437, thence through the side-switch-wiper 165 of the second-selec-
 75 tor to the contact-point 191, thence through the conductor 466, vertical-line-wiper 173, vertical-trunk-conductor 463, vertical-line-
 relay 318 of the connector C, conductor 467, winding 335 of the differential-relay 333, 80
 conductors 468, 469, 470 and 471 to the non-grounded terminal of battery B² and to ground G². The vertical-line-relay, after attracting its armature 319, closes the
 85 springs 320 and 321 into electric contact and establishes an energizing circuit through the vertical-magnet 261 of the connector. The energizing circuit passes from ground G¹³ through the springs 321 and 320, con-
 90 ductor 472, private-springs 291 and 290, con-
 ductor 473, side-switch-wiper 302, contact-
 point 306, conductor 474, vertical-magnet 261, conductors 470 and 471 to the non-
 95 grounded terminal of battery B² and to ground G². The vertical-magnet, on at-
 tracting its armature twice in the same man-
 ner that the previous selectors have operated
 their shafts, raises the shaft 252 two steps, and places the connector-wipers 253, 254 and
 100 255 opposite the first contact of the second
 level of their corresponding banks. The calling subscriber then presses the rotary-
 button 30 once, grounds the rotary-line-con-
 ductor 414 once, energizes the rotary-line-
 relay 201 and differential-relay 209 of the
 105 repeater R once, which former in turn
 grounds the rotary-trunk-conductor 439 once. Said conductor extending to the connector causes the magnetizing of the rotary-
 line-relay 324. The current in this last cir-
 110 cuit flows from ground G⁸ to the rotary-
 trunk-conductor 439, through the second-
 selector-side-switch-wiper 179, contact-point
 192, conductor 475, rotary-line-wiper 174,
 trunk-conductor 464, rotary-line-relay 324,
 115 conductor 476, winding 336 of the differen-
 tial-relay 333, conductor 477, back-bridge-
 relay-springs 343 and 344, conductors 469,
 470 and 471 to the non-grounded terminal
 of battery B² and to ground G². The con-
 120 nector-line-relay-springs 326 and 321 being
 thereby connected together the private-mag-
 net 281 is energized by a current flowing
 from the ground G¹³ through said springs
 321 and 326, conductor 478, private-magnet 125
 281, conductors 479 and 477, back-bridge-
 relay-springs 343 and 344 to the non-
 grounded terminal of battery B² and to
 ground G². The connector-private-magnet
 being energized once attracts its armature 130

once, which latter permits the connector-side-switch to pass to second position, the side-switch-wiper 302 passing from the contact-point 306 onto the contact-point 307, 5 and the side-switch-wiper 303 from the contact-point 309 onto the contact-point 310. The shifting of the side-switch-wiper 302, as stated, produces a change in circuits in the connector, then when the vertical-button 29 10 is pressed ten times for the last digit, and the energization of the vertical-line-relay 318 results ten times, over a circuit already pointed out, the rotary-magnet 277, instead of the vertical-magnet 261, is operated when 15 the springs 320 and 321 are brought into contact. Each time that the springs 320 and 321 close, a current passes from the ground terminal G^{13} through the springs 321 and 320, through the private-springs 291 and 290 to the side-switch-wiper 302, 20 passing through which it then extends through the contact-point 307 to the conductor 480, thence through the rotary-magnet 277 to the non-grounded terminal of 25 battery B^2 to ground G^2 . At each pulsation, the rotary-magnet attracts its armature 278, rotating the shaft 252 one step at a time, sliding the wipers 253 and 254 along the second level of the bank with which they 30 engage. At the end of the tenth pulsation, the wipers are landed onto the tenth contact-terminals of the second level. For the last time the rotary-push-button 30 is pressed once, the rotary-conductor 414 is 35 grounded once, the rotary-line-relay 201 and differential-relay 209 of the repeater are energized, and as a result the rotary-trunk-conductor 439 is grounded once. Again the rotary-line-relay 324 of the connector is 40 energized once, the said relay in turn producing the operation of the private-magnet 281 that permits the side-switch to pass into third position with the side-switch-wipers 302, 303, 304 and 305 in contact with 45 the contact-points 308, 311, 314 and 317, respectively. The engagement of the side-switch-wiper 303 with the contact-point 311 places a guarding potential at the private-wiper 255, and at the tenth private-contact of the second level of the 50 private-bank 251, to preclude any other connector from entering into connection with the called line #2420. It will be understood, of course, that the same guarding potential exists at all other private-bank contacts in multiple with the private-bank contact mentioned. The closure of contact between the side-switch-wipers 304 and 305 and contact-points 314 and 317, respectively, 55 60 connects the extended subscriber's line-conductors 463 and 464 through the condensers 345^a and 346 with the vertical and rotary line-wipers 253 and 254, and, therefore, with the normal-conductors 481 and 482 that constitute the terminals of the called sub-sta- 65 tion #2420. The calling first-selector, it will be remembered, places a guarding potential over its own line at the connector-private-bank-contacts that correspond to the substation #7000, at the instant that the off-normal-spring 66 comes into contact 70 with the grounded spring 68. Later, and at the instant that the connector seizes on the called subscriber's normal-conductors 481 and 482, the calling connector places a 75 guarding potential over the called line at the instant that the side-switch-wiper 303 engages with the contact-point 311. Evidently, then, a line is protected by a guarding potential, either when calling or when 80 called, in the former case by operations in the first-selector, and in the latter case by the connector. The establishment of a guarding potential for the called line #2420 not only protects it from further seizure, 85 but also forces a current through the bridge-cut-off-relay 350 of the called first-selector F^2 , in order that the latter, by its armature, may separate the bridge-cut-off-relay-springs 351, 352 and 353. The separation 90 of the said springs from each other destroys a bridged circuit through the vertical and rotary line-relays 354 and 355, and that normally extends across the line-conductors 483 and 484, and at the same time interrupts a 95 connection between said relays 354 and 355 and the non-grounded terminal of the battery B^2 , which terminal is directly connected with the spring 353. Since the conductors 483 and 484 are included, one on 100 each side of the main talking circuit, as will hereinafter be disclosed, it is desirable to remove all unnecessary bridges from across said conductors, for obvious and other reasons to be described, and at the same time 105 to remove all possibility of the vertical and rotary line-relays being energized when a ringing current is projected to the called sub-station, so that no undesirable interruptions may take place thereby. The energizing circuit through the bridge-cut-off-relay 350 extends from ground G^{14} to the connector-side-switch-contact-point 311, side-switch-wiper 303, conductor 485, private-wiper 255, private-normal-conductor 486, spring 356, contact-point 357, conductor 487, and bridge-cut-off-relay 350 to the non-grounded terminal of battery B^2 110 and to ground G^2 . In each preceding case where the rotary and vertical line-relays 318 and 324 have been energized, the differential-relay 333 has been energized also, but it has had no part in the useful operations of the switch as yet. The connection between the calling and called line having been established, the calling party is in a position 115 to signal the called line by means of his signaling button 12. But before going any further it will be explained that if for any reason the called line is busy at the time 120 125 130

that the calling subscriber grounds the rotary-line-conductor 414 for the last time, to transfer the connector-side-switch from second to third position, the connector necessarily is released. For instance, if the line #2420 has been called by another connector, there will be a guarding potential at the tenth private-contact of the second level of the private-bank 251, corresponding to the line of the sub-station #2420. Or, on the other hand, if the first-selector F² of the called line is being used, and the shaft of said first-selector is off-normal as a result, the same private-bank-contact will be connected to ground from the instant that the normal-post-arm 358 permits the off-normal-spring 356 to engage with the grounded contact-point 359. Said guarding potential will reach the private-bank of the connector by way of the private-normal-conductor 486. At any rate, if the private-wiper 255 finds a guarding potential at the tenth contact of the second level of the private-bank 251, at the instant that the calling subscriber grounds his rotary-line-conductor 414 for the last time, it follows that instead of the side-switch being tripped to third position the connector will be released because the energization of the private-magnet 281 as a final result of grounding the rotary-line-conductor 414 sets up an energizing circuit through the release-magnet of the connector when the armature of the said private-magnet forces the springs 292 and 293 into contact. The energizing circuit through the release-magnet allows the current to flow from the grounded terminal of the battery B² to the tenth contact of the second level of the connector-private-bank 251 through the private-wiper 255, conductor 485, side-switch-wiper 303, contact-point 310, conductor 488, private-springs 292 and 293, conductors 489 and 490, release-magnet 265, conductor 491, springs 342 and 340, to the non-grounded terminal of battery B² and to ground G². It will be noticed that the release-circuit passes through the springs 342 and 340 of the differential-relay 333, which springs are normally apart. But it will be remembered that the said differential-relay becomes energized when the calling subscriber #7000 grounds the rotary-line-conductor 414. Therefore, at the same time that the private-magnet closes the private-springs 292 and 293, the differential-relay closes the said springs 340 and 342. The connector-release-magnet being energized, the release-armature 266 moves the double-dog 268 so that the lug 274 is caught and held in the aperture 276 on the end of the release-link. Of course, when the double-dog is thus rotated, the locking-arm 272 is withdrawn from the longitudinal teeth 257. Then the shaft is free to be rotated back to its normal rotary position, by the tension of the coiled spring 260, until the normal-post-arm 259 strikes the normal-post 347. At that instant the shaft-support 348 enters the slot or groove 349, and the shaft of necessity then falls to its normal position. The release-armature, when it rotates the double-dog 268, at the same time drives the side-switch to its first position, about the pivots of the latter, by means of the side-switch-link 301 and the release-arm 273. This latter, by pressing the former back, forces the escapement-finger 295 back between the escapement-springs 283 and 284, which latter is then caught behind the rearmost lower tooth 287 where it remains until the connector comes into use again. The restoration of the connector-shaft takes place while the release-magnet 265 is in an energized state; but, since the energizing circuit through said magnet 85 comprises the private-wiper 255 and the side-switch-wiper 303, it will be evident that as soon as the shaft begins to rotate to its normal position the energizing circuit through the release-magnet 265 will be broken as soon as the said private-wiper 255 leaves the private-contact-point with which it has been engaged. The same energizing circuit is also interrupted at the side-switch-wiper 303 when the latter is forced into its first position. The subscriber then, thinking he has established connection, presses the signaling button 12 at his sub-station, with the result that the spring 11 is separated from the contact-point 10 and closed in connection with the grounded contact-point 35. The said spring 11 being in direct electrical communication with the vertical-line-conductor 402, through the primary springs 13 and 14, and through the contact-point 31 and spring 33, it follows that the pressing of the button 12 grounds the vertical side of the line. The grounding of the vertical-line causes the energizing of the connector-vertical-line-relay 318 in the usual manner; and since the connector-side-switch is in first position, the connector-vertical-magnet 261 is energized, when the line-relay-springs 320 and 321 are pressed into contact through a circuit that is already familiar. As a result, and for reasons previously described, the shaft of the connector is raised and the springs 198 and 197 which it controls are brought into contact. The engagement of these two parts completes a busy circuit through which the busy signaling current is transmitted to the calling sub-station, which current may originate in any suitable apparatus, such as that represented at F, Fig. 2, which comprises a coil 362 in which latter the said busy current is induced. The subscriber, having been instructed, will understand that the line he desires is busy. This busy current passes from the coil 362 to the conductor 492, through

the springs 198 and 197, conductor 493, contact-point 315, side-switch-wiper 305, springs 329 and 328, conductor 494, condenser 346, conductor 464, wiper 174, conductor 475, 5 side-switch-wiper 179, trunk-conductor 439, conductor 443, springs 219 and 218, winding 232 of the repeating-coil 228, condenser 234, winding 230 of the repeating-coil 227, trunk-conductor 437, wiper 165, conductor 10 466, wiper 173, trunk-conductor 463, vertical-line-relay 318, winding 335 of the differential-relay 333, conductors 468, 469, 470 and 471, back to the coil 362. The subscriber will then restore his receiver to its 15 switch-hook, thereby grounding both the line-conductors 402 and 414, as before described. The grounding of these two conductors causes a simultaneous energizing of the rotary and vertical line-relays 318 and 324 of the connector, which relays, attracting their armatures 319 and 325 simultaneously, permit the connector-trunk-release-springs 322 and 323 to come together. The 20 engagement of said release-springs forces an energizing circuit through the connector-release-magnet 265, and through the second-selector-back-release-relay 187, in which circuit the current flows from the ground terminal G^{12} to the second-selector-side- 25 switch-contact-point 190, side-switch-wiper 188, second-selector-back-release-relay 187, private-wiper 175, release-trunk-conductor 465, connector-release-springs 322 and 323, conductors 495 and 490, connector-release- 30 magnet 265, conductor 491, differential-relay-springs 342 and 340, to the non-grounded terminal of battery B^2 and to ground G^2 . In this release-circuit the normally-separated differential-relay-springs 342 and 340 are included; but it should be 35 noted that when the trunk-conductors 437 and 439 are grounded at the same time, the current then flows through the windings 335 and 336 of the differential-relay 333, so that 40 the magnetic effects developed by each coil reinforce or augment each other. Therefore, when the line-relays 318 and 324 are energized simultaneously, in the release described, the differential-relay 333 is also 45 energized, and the spring 340 is, therefore, in electric connection with the spring 342. Since the release-magnet of the connector and the back-release-relay of the second-selector S become energized, it will be evident that 50 both the connector and the second-selector will be released in a familiar manner. Furthermore, the first-selector F^1 will also be released in a way that has also been pointed out. But it has also been described that the 55 calling subscriber did not find the line #2420 busy, and that he did complete his connection with said line. After doing so, he presses his signaling button 12 in the manner already stated, and thereby grounds 60 the vertical-line-conductor 402. The ground- 65 ing of said conductor energizes the vertical-line-relay 318 by means and circuits already familiar. Since the side-switch of the connector is in third position, and since the connector-side-switch-wiper 302 is in engagement with the contact-point 308, the engagement of the line-relay-springs 320 and 321 energizes the connector-ringer-relay 199. The energizing current passes from ground G^{13} through the springs 321 and 70 320, private-springs 291 and 290, side-switch-wiper 302, contact-point 308, ringer-relay 199, differential-relay-springs 342 and 340 (the differential-relay is now energized) to the non-grounded terminal of battery B^2 75 and to ground G^2 . The ringer-relay-armature 327 then forces the ringer-relay-springs 329 and 331 onto the ringer-relay-generator-springs 330 and 332. A signaling current then passes out of the subscriber's line from 80 the ringer-generator J to the brush 363, springs 332 and 331, side-switch-wiper 304, contact-point 314, conductor 496, vertical-wiper 253, vertical-normal-conductor 481, vertical-line-conductor 483, spring 364, contact-point 365, condenser 366, ringer 367, ringer-springs 368 and 369, contact-point 370, spring 371, rotary-line-conductor 484, rotary-normal-conductor 482, rotary-wiper 254, conductor 497, contact-point 317, wiper 90 305, ringer-relay-springs 329 and 330, brush 372 to ringer-generator J. The bell at the sub-station will be rung as long as the calling subscriber presses his button, but as soon as he releases said button, the ringer-relay 100 199 will then be deenergized, and the ringer-relay-springs will then return to their normal positions. Then, if the subscriber at the called sub-station removes his receiver 105 373 from the switch-hook 374, the primary-circuit-springs 375 and 376 will be brought into electrical engagement, and the ringer-circuit-springs 368 and 369 will be separated as the switch-hook rises. At the instant that the primary-circuit-springs 375 and 376 110 close, the back-bridge-relay 334 of the connector is energized through a circuit comprising said springs. The current in this case passes from the ground terminal G^{14} to the connector-side-switch-contact-point 311, 115 side-switch-wiper 303, conductor 498, winding 338 of the back-bridge-relay 334, conductors 499 and 494, ringer-relay-springs 328 and 329, side-switch-wiper 305, contact-point 317, conductor 497, rotary-line-wiper 254, rotary-normal-conductor 482, rotary-line-conductor 484, spring 371, contact-point 370, primary winding 377 of the induction-coil 378, transmitter 379, signaling button 120 springs 380 and 381, private-circuit-springs 125 375 and 376, contact-point 365, spring 364, vertical-line-conductor 483, vertical-normal-conductor 481, vertical-line-wiper 253, conductor 496, contact-point 314, side-switch-wiper 304, conductors 500 and 501, winding 130

- tact point 157, conductor 425, vertical-line-wiper 53, vertical-trunk-conductor 421, conductor 503, winding 229 of the repeating-coil 227, condenser 233, winding 231 of the repeating-coil 228, conductor 504, rotary-trunk-conductor 422, rotary-line-wiper 54 of the first-selector F¹, conductor 426, contact-point 158, side-switch-wiper 144, rotary-line-conductor 414, spring 34, contact-point 32, 5 back to the primary winding 7. The talking current is then induced in a second circuit that comprises the winding 230 of the repeating-coil 227, the vertical-inter-station-trunk-conductor 437, sideswitch-wiper 165 10 of the second-selector S, contact-point 191, conductor 466, vertical-line-wiper 173, vertical-conductor 463, condenser 345^a, conductor 500, side-switch-wiper 304, conductor 496, vertical-line-wiper 253, vertical-normal-conductor 481, vertical-line-conductor 483, 15 spring 364, contact-point 365, primary-circuit-springs 376 and 375, signaling-button-springs 381 and 380, transmitter 379, winding 377 of the induction-coil 378, contact-point 370, spring 371, rotary-line-conductor 484, 20 rotary-normal-conductor 482, rotary-line-wiper 254, conductor 497, contact-point 317, side-switch-wiper 305, ringer-relay-springs 329 and 328, conductor 494, 25 condenser 346, rotary-trunk-conductor 464, rotary-wiper 174 of the second-selector S, conductor 475, contact-point 192, side-switch-wiper 179, inter-exchange rotary-trunk-conductor 439, conductor 443, differential-relay-springs 219 and 218 of the repeater R, conductor 442, winding 232 of the repeating-coil 228, condenser 234 and to the winding 230 of the repeating-coil 227 again. It is 30 evident, then, that normally the current for energizing the talking apparatus at the calling and called sub-stations is controlled from the called sub-station by the switch-hook of the latter, by means of the primary-circuit-springs 375 and 376. 35 As pointed out, when these two springs close the back-bridge-relay 334 is energized. This latter then closes a second circuit, as a result, through the pole-changing-relay 213, which latter in turn closes a third circuit 40 that provides the calling sub-station with the required electric current. It will be evident that if the calling subscriber, after the called subscriber removes his receiver from its hook, were to press his signaling button 45 12 the circuit providing current to the called sub-station would be destroyed as soon as the spring 11 leaves the contact-point 10. At that instant the rotary and vertical line-relays 200 and 201 of the repeater will be 50 deenergized, and as soon as the signaling spring 11 closes onto the grounded contact-point 35, the vertical-line-conductor will be grounded. As a result, of course, the vertical-line-relay 200 of the repeater R and the 55 differential-relay 209 will become energized.

As soon as the differential-relay is energized, the differential-relay-springs 218 and 219 will be separated, and the energizing circuit through the pole-changing-relay 213 and the connector-line-relays is in turn 70 opened up or temporarily destroyed. As a result of the deenergizing of this last relay—the pole-changing-relay 213—the energizing circuit through the auxiliary-relay 222 is also opened or destroyed with the result 75 that the connection between the repeater-line-relay-ground-spring 205 and the ground terminal G⁸ is reestablished, as well as the connection between the rotary-line-relay-spring 206 and the rotary side of the 80 inter-exchange trunk-line 439. Immediately, then, there follows a grounding of the vertical-inter-exchange-trunk-conductor 437, since the vertical-line-relay of the repeater is energized, with the result that the vertical-line-relay 318 of the connector and the differential-relay 333 become energized. As soon as the connector-differential-relay becomes energized the differential-relay springs 340 and 341 are separated as a final 90 result and the energizing current for the talking apparatus of the called sub-station is interrupted, at which instant the back-bridge-relay 334 becomes deenergized. Naturally, then, from the energizing of the 95 connector-vertical-line-relay 318 there follows the energization of the ringer-relay 199 and a projection of ringing current over the called line again. However, as soon as the signaling button 12 is released the original 100 circuits for energizing the talking apparatus are reestablished. Incidentally, then, said ringing current is also under the control of the calling sub-station. After the two subscribers have communicated, the exchange 105 apparatus may then be released if the calling subscriber restores his receiver to the switch-hook. The restoration occurs in the following manner: The calling subscriber, on restoring his receiver, grounds both of his 110 line-conductors as a result. The rotary-line-relay 201 and the winding 211 of the differential-relay 209 become short-circuited through ground. This short-circuit extends from the ground terminal G¹⁵ through the 115 pole-changing-relay-springs 216 and 212, through the differential-relay-winding 211, rotary-line-relay 201, to the rotary-line-conductor 414 and to the ground terminal G⁸. Of course, and at once, the current that has 120 been flowing through these two coils is cut off, and as a result the rotary-line-relay 201 becomes deenergized, while the differential-relay 209 becomes energized. The energizing of the differential-relay, it will be evident, accompanied by the energization of the vertical-line-relay 200, is due to the 125 grounded condition of the vertical-line-conductor 402. As soon as the differential-relay becomes energized the differential-relay- 130

springs 221 and 220 are brought into contact, while the differential-relay-springs 218 and 219 are separated. The separation of the last two is followed, as already pointed out, by a deenergization of the pole-changing-relay 213, and of the auxiliary-relay 222, together with the deenergization of the connector-line-relays 318 and 324. But at the instant that the auxiliary-relay 222 fully regains its normal condition the ground connection to the ground-spring 205 is restored to the repeater, with the result that the vertical-inter-exchange-trunk-conductor 437 is grounded, since the vertical-line-relay 200 is energized. Furthermore, as soon as the pole-changing-relay regains its normal condition, the spring 212 passes into engagement again with the spring 214, which latter is permanently connected with the non-grounded terminal of battery B¹. Then there follows at once an energization of the rotary-line-relay 201 of the repeater, since the rotary-line-conductor of the calling substation is grounded. Of course, the energizing current passes through the winding 211 of the differential-relay 209 of the repeater; but it will be noticed that the current in this instance is flowing in a reversed direction and, therefore, the energized condition of the differential-relay 209 is not destroyed when this current is established, but on the contrary it is more strongly energized than before. The repeater vertical and rotary line-relays being again in an energized condition at the same time, the trunk-releasing-springs 207 and 208 are forced into contact, and this while the differential-relay-springs 221 and 220 are in engagement. And there, of course, follows the energizing of the back-release-relay 81 of the first-selector, and as a result the energization of the release-magnet of the first-selector also. It will be clear that when the rotary-line-relay of the repeater reenergizes, a ground will also be put on the rotary side of the inter-exchange-trunk-line, both sides of said trunk-line being retained grounded for a time simultaneously. As soon as the vertical-inter-exchange-trunk-conductor 437 is grounded, the connector-vertical-line-relay 318 and differential-relay 333 then both become energized. As soon as the differential-relay becomes energized, the springs 341 and 340 are forced apart, upon which separation there follows a deenergization of the back-bridge-relay 334. As soon as this back-bridge-relay is deenergized the spring 343 falls back into engagement with the spring 344, by which operation a circuit is reestablished through the rotary-line-relay 324, winding 336 of the differential-relay 333 and the non-grounded terminal of the battery B². The rotary-trunk-conductor 439 being grounded as soon as this union takes place the said rotary-line-relay also becomes energized. It will be noticed that even before the line-relays are in the energized condition, the energizing current through the rotary-line-relay passes through the winding 336 of the differential-relay 333, but in such a direction that the differential-relay is maintained energized. Since the trunk-release-springs 322 and 323 of the connector are thus held together, while the differential-relay-springs 342 and 340 are in contact, the releasing energizing circuit through the connector-release-magnet 265, and through the back-release-relay 187 of the second-selector S, is established with the result that the connector-release-magnet becomes energized, restoring the connector-side-switch and shaft. As soon as the connector-shaft is released the energizing circuit through the bridge-cut-off-relay 350 of the first-selector F² is destroyed or opened up, and said first-selector is thus rendered operative. Of course, at the same time that the connector-release-magnet 265 is energized, the back-release-relay 187 of the second-selector also becomes energized, as already described, with the result that the release-magnet of the second-selector also becomes magnetized. All this occurs while the switch-hook of the calling subscriber is descending, and while the release-springs 25, 26 and 27 are maintained in contact. But as soon as the release-cam clears the release-springs the ground to the vertical and rotary line-conductors 402 and 414 is destroyed. There follows, then, a restoration of the repeater-line-relays, and of the repeater-differential-relay, which destroys the continuity of the energizing circuit through the first-selector-back-release-relay, and as a result the energizing circuit through the first-selector-release-magnet is opened. It is clear, then, that the restoration of the first-selector follows. When the repeater-line-relays are restored, the ground connections to the inter-exchange trunk-conductors are interrupted, the connector-line-relays and differential-relay are deenergized, and as a result the release energizing circuit through the connector-release-magnet and the second-selector-back-release-relay is broken. Then the second-selector is restored, as well as all of the relays of the connector that have remained energized even after the side-switch and shaft have assumed their normal position.

A practical arrangement of the exchanges with respect to each other which may be employed, but to which I do not confine myself, is as follows: The sub-stations at central #1 are numbered up through 5999, and the subscribers of the exchange #2 from 6,000 to 10,000, inclusive. The first-selector-banks are provided with ten trunks from each level, as is customary, said trunks being common to all first-selectors of the same group.

The trunks of each of the first five levels terminate each in a second-selector; those of the first level in second-selectors of one group; those of the second level in second-selectors of a second group; those of the third in a third group, and so on through the fifth level. The second-selector-banks, of course, will have trunks from their levels arranged to correspond with suitable groups of connectors. The last five levels of the said first-selector-banks are given trunks similar to those of the first five levels, each of which trunks terminates in a repeater of the type described and each repeater having 10 permanently connected to it an inter-exchange trunk-line as described. Each of said inter-exchange trunk-lines terminates in the second-selector at exchange #2. The trunks of each of the last five levels terminate in groups of repeaters, one group to each level, and, therefore, with groups of second-selectors at exchange #2 that are, it will be understood, suitably arranged with respect to the connector groups, as are the 15 second-selectors of exchange #1. At exchange #2 a similar arrangement prevails, except that the repeaters are connected to the first five levels through which the connectors at exchange #1 are reached. The 20 last five levels, of course, are used for calling local subscribers. It has been found in practice that good results are obtained when the repeater-coils 200 and 201 are wound to a resistance of about 125 ohms each, the differential-relay-windings 210 and 211 to 250 ohms each, the pole-changing-relay 213 to 150 ohms, the auxiliary-relay to 500 ohms and the resistance-coil 235 to 60 ohms. It 25 is evident that with a back-release-relay of $\frac{1}{2}$ ohm the resistance-coil 235 in the repeater is essential to avoid an excessive rush of current through the said back-release-relay when a circuit is completed. In the connector the line-relays 318 and 324 are 30 wound to a resistance of 125 ohms each, while the windings 336 and 335 of the differential-relay 333 are wound to a resistance of 250 ohms each. Also, the back-bridge-relay has each of its coils 337 and 338 wound 35 to a resistance of 375 ohms.

There is nothing new about the first-selectors, by themselves, and the system as a whole is a trunk-release system. The first-selector F¹ is released in a familiar manner 40 when the line-relays 200 and 201 of the repeater are energized simultaneously. The releasing circuit comprises the back-release-relay 81 of the first-selector in series with the trunk-release-springs 207 and 208 of the 45 repeater, which are normally open, and in series with the dead-resistance-coil 235 of 60 ohms, preferably, and the differential-relay-springs 221 and 220. It is evident that this release-circuit through relay 81 50 has two normally-open switch-points, one at the trunk-release-springs 207 and 208, and another at the differential-relay-springs 221 and 220. Furthermore, it will be evident that the ground connection in this circuit is obtained when the side-switch-wiper 142 of the first-selector F¹ is in third position. While the two subscribers are talking, however, one of the normally-open points in the release circuit is closed. Of course, when the line-relays 200 and 201 of the repeater 55 become energized simultaneously the inter-exchange trunk-conductors 437 and 439 are then grounded simultaneously, but not while the auxiliary - relay is energized. The grounding of these two conductors, in the 60 manner described, will energize the line-relays 318 and 324 of the connector C, which relays, as usual, when thus energized, close together the trunk-release-springs 322 and 323. The release circuit of the connector 65 comprises the back-release-relay 187 of the second-selector S, the trunk-release-springs 322 and 323 of the connector, the release-magnet 265 and the differential - relay - springs 342 and 340. This local connector 70 release circuit also, it will be seen, has two normally-open switch-points, one at the trunk-release-springs, and another at the differential-relay-springs, the former closed during talking. A feature of the connector 75 is that the release-magnet 265 is normally disconnected from the non-grounded terminal of the battery. Therefore, the connector cannot be released until the differential-relay 333 is energized for the purpose of 80 closing the differential-relay-springs 342 and 340, so that current through the release-magnet may reach the non-grounded terminal of battery. Still another feature is the winding of the back-bridge-relay-coils 337 and 338 on one core to form one relay; and another feature of the connector is that the private-magnet 281, and the rotary-line-relay 324 through the winding 336 of the differential-relay 333, reach the non-grounded 85 terminal of the battery through two springs 343 and 344 of the back-bridge-relay 334. This double-wound back-bridge-relay may 90 also be termed a pole-changing-relay, since when the side-switch-wiper 303 is in third 95 position the spring 345 is connected directly to ground, and since the spring 344 is permanently connected to the non-grounded terminal of the battery. There is a modification in the connection between the condenser 345 in the vertical side of the talking circuit of the connector and the connector-vertical-line-wiper 253. It will be 100 seen that the said condenser is directly connected with the vertical-line-wiper 253 when the side-switch-wiper 304 is in third position. Ordinarily, the connection between the condenser and vertical-line-wiper is usually completed through two of the ringer-relay-springs. This improvement does away 105 110 115 120 125 130

with one of the usual ringer-relay-springs. However, when the ringer-relay is energized, the calling line is no longer absolutely severed from connection with the called line 5 while ringing current is being sent over the called subscriber's line. It will be noticed that the operation of releasing before the called subscriber has removed his receiver from its hook is different from the release 10 after the said subscriber has answered. In the former case, immediately upon the grounding of the line-conductors 402 and 414, the line-relays 200 and 201 of the repeater are energized together with the differential-relay 209. In turn the trunk-conductors 437 and 439 are grounded by the said line-relays, and as a result the connector-line-relays and differential-relay are energized. In the latter case, however, upon the 15 grounding of the two line-conductors 402 and 414, while talking current is flowing over the lines, the vertical-line-relay 200 of the repeater remains magnetized, and for an instant the rotary-line-relay 201 and one of the windings 211 of the differential-relay 209 become short-circuited and the current through these two coils ceases to flow. The 20 cessation of current through the winding 211 of the differential-relay 209 leaves said relay solely to the influence of the winding 210, and said relay at once energizes. Upon the energization of the differential-relay there follows immediately a number of steps. The energizing circuit that has been in action 25 during conversation, and which comprises the pole-changing-relay 213 of the repeater, the line-relays 318 and 324 of the connector, and both windings 335 and 336 of the differential-relay 333 of the connector, is destroyed as soon as the springs 218 and 219 are forced apart. As a result, there 30 immediately follows the deenergization of the connector-line-relays and of the repeater-pole-changing-relay. The deenergization of the latter produces two effects: First, the 35 circuit through the auxiliary-relay 222 is destroyed, which latter at once restores ground connection to the ground-spring 205 of the repeater-line-relays 200 and 201; and, second, a new circuit is established through 40 the repeater-rotary-line-relay 201 and the repeater-differential-relay-winding 211, as soon as the pole-changing-relay-spring 212 falls against the spring 214. The reenergizing of the rotary-line-relay 201 immediately 45 occurs, together with the strengthening of the already magnetized differential-relay 209. There follows, also, the grounding of the inter-exchange trunk-conductors, because of the deenergization of the auxiliary-relay 222, and as a result the line-relays and the differential-relay of the connector 50 become magnetized. The connector at once releases and restores the bridge-cut-off-relay 55 of the first-selector F². As soon as the re- lease-springs at the calling sub-station disengage, however, there follows immediately a simultaneous deenergization of all relays and magnets, followed by the restoration of all described parts. Clearly, then, in releasing 60 when the called sub-station has not answered all the relays which are energized during talking are magnetized at once; but in releasing when the subscriber has answered, there first occurs a cessation of the flow of current through the winding 211 of the differential-relay 209, and an energization, as a result, of the differential-relay 209 simultaneously with a deenergization of the rotary-line-relay 201. The energization of the differential-relay then produces, first, a deenergization of all energized relays except the vertical-line-relay 200 of the repeater, followed immediately by an energization of all relays and magnets that take part in the releasing of the whole system. This amounts to first destroying the circuits that establish talking battery to both the calling and called sub-stations, followed by the temporary establishment of new circuits 90 preliminary to the release. It will also be noticed that when the subscribers are talking, as far as the voice-currents are concerned, the two sub-stations are connected through three inductive circuits. The first 95 one comprises in series the sub-station #7000, transmitter 9 and the repeater-windings 229 and 231, with the condenser 233 in between. The second circuit comprises the windings 230 and 232 and the condenser 100 234 of the repeater R and terminates in the connector-condensers 345^a and 346. The third comprises the transmitter 379 at the called sub-station and terminates in the said condensers 345^a and 346. As far as the battery B¹ is concerned, the first inductive circuit is divided into a conductive circuit and inductive circuit connected in multiple. As far as the battery B² is concerned, the third 105 circuit is likewise divided into a conductive and an inductive circuit in multiple; while the second inductive circuit is divided by the battery B² into a conductive and two inductive circuits, said inductive circuits being connected in multiple and bridged across the 110 said conductive circuit. Furthermore, the first of the three inductive circuits is connected inductively with the second inductive circuit, while the second is connected inductively with the third. 115 It will be understood that the selectors herein described and illustrated can be of the general type disclosed in Patent No. 815,321, granted March 13, 1906, to Keith, Erickson & Erickson. It will also be understood that the connectors herein referred to can be of the general type disclosed in Patent No. 815,176, granted March 13, 1906, to Keith, Erickson & Erickson. Obviously, 120 the various details and features of my in- 125 130

vention are susceptible to considerable change or modification without departing from the spirit thereof.

What I claim as my invention is:—

- 5 1. A common battery automatic telephone exchange system comprising a first-selector, a second selector, means for controlling said selectors, repeating-coils in a trunk for connecting one selector with the other, and means whereby calling impulses in the trunk at one side of the said coils are repeated in the trunk at the other side thereof. 70
- 10 2. A common battery automatic telephone exchange system comprising a subscriber-controlled trunk-selecting switch, another subscriber-controlled trunk-selecting switch, means at the substation for controlling said switches, repeating-coils in a trunk for connecting the two switches together, and means 75 whereby calling impulses in the trunk at one side of the said coils are repeated in the trunk at the other side thereof. 80
- 15 3. A common battery automatic telephone exchange system comprising an electrically-propelled and step-by-step-actuated switching machine, another electrically-propelled and step-by-step-actuated switching machine, means for controlling said machines, repeating-coils in a trunk for connecting the two switching machines together, and means 85 whereby calling impulses in the trunk at one side of the said coils are repeated in the trunk at the other side thereof. 90
- 20 4. A common battery automatic telephone exchange system comprising a first-selector, a second-selector, means for controlling said selectors, repeating-coils and condensers in a trunk for connecting one selector with the other, and means whereby calling impulses 95 in the trunk at one side of the said coils are repeated in the trunk at the other side thereof. 100
- 25 5. A common battery automatic telephone exchange system comprising a subscriber-controlled trunk-selecting switch, another subscriber-controlled trunk-selecting switch, means at the substation for controlling said switches, repeating-coils and condensers in a trunk for connecting the two switches together, and means whereby calling impulses 105 in the trunk at one side of the said coils are repeated in the trunk at the other side thereof. 110
- 30 6. A common battery automatic telephone exchange system comprising an electrically-propelled and step-by-step-actuated switching machine, another electrically-propelled and step-by-step-actuated switching machine, means for controlling said machines, repeating-coils and condensers in a trunk for connecting the two switching machines together, and means whereby calling impulses 115 in the trunk at one side of the said coils are repeated in the trunk at the other side thereof. 120
- 35 7. A common battery automatic telephone exchange system comprising a first-selector provided with a release-relay, a repeater provided with a pair of line-relays and a differential-relay, together with a trunk-release energizing circuit for said release-relay, said circuit having two normally-open switch-points whereof one is controlled directly and conjointly by said line-relays, and the other is controlled directly by said differential-relay, and means for supplying talking current to the calling line through 125 said line relays. 130
- 40 8. A common battery automatic telephone exchange system comprising a trunk selecting switch mechanism provided with a release-relay, a repeater provided with a pair of line-relays and a differential-relay, and a trunk-release energizing circuit for said release-relay, said energizing circuit having two normally-open switch points whereof one is controlled directly and conjointly by said line-relays, and the other is controlled directly by said differential-relay, and means for supplying talking current to the calling line through said line relays. 130
- 45 9. A common battery automatic telephone exchange system comprising a line-circuit provided with a repeater, said repeater being provided with means for inductively dividing the line-circuit, and having a differential-relay for opening the voice current circuit at one side of the inductive connection. 130
- 50 10. A common battery automatic telephone exchange system comprising repeating-coils and condensers, a line-circuit for voice-currents, said line-circuits being inductively divided by said coils and condensers into inductively-connected portions, and a differential-relay connected with the line-circuit at one side of said inductive connections and controlling the line-circuit at the other side of the same. 130
- 55 11. A common battery automatic telephone exchange system comprising a line-circuit, a repeater provided with repeating-coils and condensers dividing the line-circuit into inductively-connected portions, said repeater having a pair of line-relays, and a third relay connected with the line-circuit at one side of the inductive connections, and normally-open connections between the line and ground and leading from the other side of said inductive connections, said ground connections being controlled by the two line-relays and the third relay. 130
- 60 12. A common battery automatic telephone exchange system comprising a line-circuit provided with a repeater, said repeater having five relay-coils normally bridged across the line-circuit, a normally-closed shunt of low resistance extending around one of said coils, and another relay for controlling said shunt. 130

13. A common battery automatic telephone exchange system comprising a line-circuit, repeating-coils dividing the line-circuit into inductively-connected portions, a battery, condensers for preventing a flow of battery current through the windings of the repeating-coils, and means including relays and ground connections for repeating electrical impulses from one portion of the line-circuit to the other. 70
14. A common battery automatic telephone exchange system comprising a connector having release mechanism operated by a release-magnet, and a battery having one pole grounded, the non-grounded pole of the battery being normally disconnected from one terminal of the said release-magnet, and the grounded pole being normally disconnected from the other terminal therefrom. 75
15. A common battery automatic telephone exchange system comprising a battery having one pole grounded, a connector having a line-circuit provided with a condenser in each side thereof, a private-magnet, a rotary-line-relay, a differential-relay, and a back-bridge-relay, said back-bridge-relay having normally-closed contacts, the rotary-line-relay having one terminal connected through said contacts and one winding of the differential-relay to the non-grounded terminal of the battery, and the said private-magnet having one terminal connected through the said contacts to the non-grounded terminal of the battery. 90
16. A common battery automatic telephone exchange system comprising a battery having one pole grounded, a connector having a line-circuit provided with a condenser in each side thereof, line-relays normally bridged across the line-circuit at one side of said condensers, with the middle point of the bridge normally connected with the non-grounded pole of the battery, and a double-wound back-bridge-relay connected with the line-circuit at the other side of said condensers and means for connecting the battery in series between the windings of the back-bridge-relay, said back-bridge-relay being provided with contacts and connections for opening the line-relay-bridge and connecting the battery in series between the coils of the latter. 100
17. A common battery automatic telephone exchange system comprising a connector provided with a pair of line-relays, a battery having one pole normally connected with the two line-relays, and a double-wound relay having means for shifting one of the line-relays into connection with the other pole of the battery, so as to include the latter in series between the two line-relays, and the connector being also provided with means for including the battery in series between the two windings of the said double-wound relay. 110
18. A common battery automatic telephone exchange system comprising a connector provided with a line-conductor, said connector being common to a plurality of lines for calling purposes, a condenser in said line-conductor, a switch-wiper in said line-conductor, a bank of line-contacts adapted to be engaged by said switch-wiper, means for controlling said connector from a distant station and a single switch-point in the line conductor between said condenser and switch-wiper, said wiper normally insulated from battery and ground. 125
19. A common battery automatic telephone exchange system comprising a connector having parallel line-circuit conducting paths, a ringer-relay having normally closed contacts controlling the continuity of only one side of the line-circuit, whereby the other side of the line-circuit is not opened when the ringer-relay is energized by any calling subscriber for putting ringing current on the called subscriber's line, means for supplying such ringing current, means for controlling said relay from a distant station, and a plurality of lines to which said relay is common for calling purposes. 130
20. A common battery automatic telephone exchange system comprising a temporarily established talking circuit having parallel vertical and rotary line-conductors, a repeater having vertical and rotary line-relays bridged across the talking circuit, a battery connected in series between the two line-relays of the repeater, a connector having vertical and rotary line-relays bridged across the talking circuit, another battery connected in series between the two relays of the connector, each battery thereby having its grounded pole connected through a so-called rotary-relay with the so-called rotary side of the talking circuit, a relay-controlled switch-point in the connection between the first-mentioned battery and the rotary-line-relay of the repeater, a relay-controlled switch-point in the connection between the last-mentioned battery and the rotary-line-relay of the connector, and grounded release-initiating circuits including the vertical side of the said talking circuit, the said connector being provided with a rotatable and endwise or vertically-movable switch-shaft, and with means whereby the vertical endwise movements of the switch-shaft are controlled by grounded circuits including the said vertical side of the talking circuit. 140
21. A common battery automatic telephone exchange system comprising a calling subscriber's station and a called subscriber's station, trunk-selecting and line-connecting switching machinery temporarily retained in position to maintain the talking circuit between the two subscribers' stations, 145

- a battery for supplying current to the line-circuit, and a repeater provided with repeating-coils in the talking circuit, said repeater being also provided with relay means 5 for repeating electrical impulses from one side of the repeating-coils to the other, and condensers for stopping the flow of battery current through said repeating-coils.
22. In a telephone exchange system, the 10 combination of a calling telephone line, a called telephone line, automatic means for trunking the calling line into connection with the called line, means for controlling said automatic means from a distant station, repeating coils in a trunk for transmitting the voice-currents between the two lines, centralized means for supplying operating current to the lines, condensers for stopping the flow of operating current through the said repeating coils, and means whereby calling impulses in the trunk at one side of the said coils are repeated in the trunk at the other side thereof.
23. In a telephone exchange system 25 equipped with automatic switches, the combination of a calling telephone line, a called telephone line, means for repeating electrical impulses from one automatic switch to a second switch for operating said second switch by which the connection is extended to the called line, and repeating coils for transmitting the voice-currents between the two lines.
24. In a telephone system, the combination 35 of means including automatic switches having vertical and rotary motion for extending connection between calling and called subscribers' lines, and repeating coils less in number than the subscribers' lines and adapted to be automatically switched into connection between calling and called subscribers' 40 lines, said repeating coils inductively connecting sections of the talking circuit, said switches associated with one of said sections, and means for repeating operating impulses 45 from one section to the other for operating said switches.
25. In a telephone system, the combination 50 of means including automatic switches having first vertical and then rotary motion for automatically trunking calling lines into connection with called lines, and repeating coils in the connections between the calling and called lines, said repeating coils inductively connecting sections of the talking circuit, said switches associated with one of said sections, and means for repeating operating impulses 55 from one section to the other for operating said switches.
26. In a telephone system, the combination 60 of automatic switches having first vertical and then rotary motion for automatically establishing talking circuits between calling and called substations, and repeating coils in the circuits between the substations, said re- peating coils inductively connecting sections 65 of the talking circuit, and switches associated with one of said sections, and means for repeating operating impulses from one section to the other for operating said switches. 70
27. In a telephone system, the combination of means including automatic switches having vertical and rotary motion for automatically trunking from one point to another, and repeating coils less in number than the 75 subscribers and adapted to be included in the said trunking connections, said repeating coils inductively connecting sections of the talking circuit, and switches associated with one of said sections, and means for repeating 80 operating impulses from one section to the other for operating said switches.
28. In a telephone system, a set of voice-current repeating coils, a switch having first vertical and then rotary motion to automatically establish connection with said repeating coils, a second switch for setting up a talking circuit to a called line, said repeating coils inductively connecting sections of the talking circuit, and means for repeating 85 90 operating impulses from one section of said talking circuit to the other for operating said switch.
29. In a telephone system, a plurality of trunks, a set of repeating coils for each 95 trunk, a switch having first vertical and then rotary motion to automatically select an idle set of repeating coils, said repeating coils inductively connecting sections of the talking circuit, an automatic progressively movable 100 switch associated with one of said sections, and means for repeating operating impulses from one section to the other for operating said switch.
30. In a telephone system, a set of voice-current repeating coils, automatic switches having first vertical and then rotary motion to extend connection to and from said repeating coils, said repeating coils inductively connecting portions of the talking circuit, 110 and a second switch for connecting with a called line.
31. In a telephone system, a set of voice-current repeating coils, an automatic switch having first vertical and then rotary motion 115 to extend connection to said coils, and another automatic switch having first vertical and then rotary motion to extend connection from said coils, whereby a talking circuit consisting of two portions is established between calling and called subscribers, said repeating coils inductively connecting said portions of the talking circuit, and means for repeating operating impulses from one portion of the talking circuit to the other 120 125 for operating one of said switches.
32. In a telephone system, a set of repeating coils, automatic means controlled over

- the line circuit for including said coils in a talking circuit between calling and called subscribers, a battery at one side of said coils for supplying talking current to the 65
- 5 calling subscriber, and another battery at the other side of said coils for supplying talking current to the called subscriber.
33. In a telephone system, means including an automatic switch having vertical motion to select groups and rotary motion to connect with a line in any selected group for including a set of voice-current repeating coils in a talking circuit between calling and called subscribers, a second switch for extending the talking circuit to a called line, said repeating coil inductively connecting portions of the talking circuit, and means for repeating operating impulses from one portion of the talking circuit to the other for 70 operating said second switch.
34. In a telephone system, a plurality of subscribers' lines, a plurality of sets of repeating coils, the number of sets being less than the number of lines, an automatic switch operative under substation control to by one motion first select a group and to then by rotary motion automatically select an idle set of repeating coils, a second switch for extending the talking circuit to a called line, 75 said repeating coil inductively connecting portions of the talking circuit, and means for repeating operating impulses from one portion of the talking circuit to the other for operating said second switch.
35. In a telephone system having repeating coil trunks, a common battery source of talking current, means for automatically selecting idle repeating coil trunks in predetermined groups to extend connection from 80 calling lines, whereby common battery talking circuits are partially established between calling and called subscribers, a second switch for connecting with a called line, said repeating coils inductively connecting portions of the talking circuit, and means for repeating operating impulses from one portion of the talking circuit to the other for operating said second switch.
36. A telephone exchange system comprising telephone lines extending from substations to a central station, link-circuits at the latter station for uniting said lines, repeating coils included in said link-circuits for inductively uniting parts thereof, switching 85 mechanism controlled from a calling station for connecting calling and called lines to opposite ends respectively of one of said link-circuits for conversational purposes, disconnecting means independent of said 90 repeating coil under the subsequent control of the connected parties for destroying the established connection and restoring all parts to normal, a central source of current, and means controlled by the response of the called subscriber for bridging said source across the calling line and placing said disconnecting means in operative relation with said calling line.
37. A telephone exchange system comprising telephone lines extending from substations to a central station, link-circuits at the latter station for uniting said lines, repeating coils included in said link-circuits for inductively uniting parts thereof, switching mechanism controlled from a calling station for connecting calling and called lines to opposite ends respectively of one of said link-circuits for conversational purposes, disconnecting means for destroying the established connection and restoring all 95 parts to normal comprising electromagnetic means included in circuit with said stations, a central source of current, and means controlled by the response of the called subscriber for bridging said source across the calling line and placing said disconnecting means in operative relation with said calling line.
38. A telephone exchange system comprising telephone lines extending from substations to a central station, link-circuits at the latter station for uniting said lines, repeating coils included in said link-circuits for inductively uniting parts thereof, switching mechanism controlled from a calling station for connecting calling and called lines to opposite ends respectively of one of said link-circuits for conversational purposes, disconnecting means for destroying the established connection and restoring all 100 parts to normal comprising electromagnetic means included in circuit with the portion of the connected link-circuit inductively united by the repeating coil, a central source of current, and means controlled by the response of the called subscriber for bridging said source across the calling line and placing said disconnecting means in operative relation with said calling line.
39. A telephone exchange system comprising telephone lines extending from substations to a central station, link-circuits at the latter station for uniting said lines, repeating coils included in said link-circuits for inductively uniting parts thereof, switching mechanism controlled from a calling station for connecting calling and called lines to opposite ends respectively of one of said link-circuits for conversational purposes, a ringing key at the calling substation, a busy 105 signaling device, means for indicating to the calling party a busy condition of the called line in response to the actuation of said ringing key by the transmission of a signal from said device, and means independent of said repeating coil for restoring said switching mechanism.
40. A telephone system comprising a line

circuit, a differential relay provided with a pair of windings, a pair of line relays, a permanently closed bridge across said line circuit, said bridge including the coils of 5 said line relays connected in series with the said windings of the said differential relay, a battery having one pole grounded, and a permanent connection between all of said relay coils and the non-grounded pole of 10 said battery.

41. In a telephone system comprising calling and called subscribers' lines, a trunk line connection between the lines, a repeater in the trunk line connection, and means for supplying all necessary current, said repeater having repeating coils for inductively transmitting voice currents, relays for repeating switch operating electric impulses, and a differentially wound relay for use by the calling subscriber in releasing, said differen- 15 20

tially wound relay having two windings normally connected with the non-grounded pole of said source of current.

42. A telephone system comprising a subscriber-operated trunk selecting switch 25 mechanism provided with a release relay, an energizing circuit for said relay, and a repeater, together with a source of operating current, said circuit having two normally open switch points controlled by said trunk- 30 selecting switch mechanism, and having also two other normally open switch points controlled by said repeater.

Signed by me at Chicago, Cook county, Illinois, this 29th day of Dec., 1905.

TALBOT G. MARTIN.
